UNITED STATES PATENT OFFICE

2,015,064

SOLE FITTING MACHINE

Frederic E. Bertrand, Lynn, Mass., assignor to
United Shoe Machinery Corporation, Paterson,
N. J., a corporation of New Jersey

Application March 7, 1933, Serial No. 659,940

96 Claims.

(Cl. 12—27)

This invention relates to improvements in sole fitting machines and is herein illustrated as embodied in a channeling machine which is particularly adapted for operating upon insoles for welt shoes and upon soles for turn shoes.

5 In United States Letters Patent Nos. 1,623,225 and 1,623,226, both granted April 5, 1927, upon applications of H. A. Ballard, and in United States Letters Patent No. 1,658,347, granted February 7, 10 1928, upon application of W. C. Meyer, there are disclosed channeling machines in which the work is fed while the cutting means is operating and an additional feed movement is imparted to the work while the cutting means is inoperative to 15 cut the work.

15 It is one object of the present invention to provide further improvements in sole fitting machines of the general type of the channeling machine above referred to for the purpose of rendering them more efficient and reliable in operation.

20 With this object in view, one feature of the present invention consists in the provision, in a sole fitting machine, of a feed device movable about an axis intersecting the plane of the sole and located at one side of the line of feed of the sole and arranged to feed upon its forward stroke, and an oscillatory knife movable about an axis intersecting the plane of the sole and located at the opposite side of the line of feed and adapted 25 to cut with a drawing action on its backward stroke during the forward movement of said feed device. The above-mentioned drawing action of the knife is due partly to the oscillatory movement of the knife which results in "drawing" the 30 knife slightly in a direction transverse to the line of work feed while the knife is moving in the general direction of the line of feed and is to be distinguished from a straight cutting action such as would be produced by a knife having a straight line reciprocating movement in the line of feed 35 of the work. In other words, the drawing action of the knife results from the fact that there is some relative movement between the knife and the work in the direction of the length of the cutting edge of the knife while the knife is cutting.

40 As embodied in the illustrated machine the sole feeding means comprises an oscillatory feed device or feed dog which operates to feed the sole over a freely rotatable work supporting table and which, like the knife, is movable about an axis intersecting the plane of the sole but which is located at the opposite side of the line of feed from the axis of oscillation of the knife. As a 45 result of the employment of such as oscillatory

5 feed device the amount of relative movement between the knife and the work lengthwise of the knife edge or, in other words, the amount of drawing action of the knife, is increased, thus making it still easier to cut and feed the work since the knife will offer only a minimum amount of resistance to the advance of the work. The movement of the oscillating knives simultaneously in opposite directions causes the inner knife at the end of each backward cutting stroke to be located 10 in advance of the outer knife, i. e., nearer to the operator than the outer. With the knives thus relatively positioned the knives will offer little if any resistance to the turning of the work inasmuch as the work in turning will pivot about the 15 tip of the outer knife so that the between substance will be caused to swing away from the inner knife. In other words, swinging of the sole establishes clearance between the between substance and the heel of the inner knife and there 20 is no crowding of the insole material against either knife. Moreover, as in the machine disclosed in Letters Patent No. 1,623,225, hereinbefore referred to, the machine herein illustrated is provided with two knives, one for forming an inner end and 25 the other for forming an outer channel in the sole, the knives cutting upon their backward strokes and moving simultaneously in opposite directions so as to cut in alternation and thus to divide the cutting strain and distribute it evenly 30 over the entire period of operation upon the work. Two feed devices or feed dogs are also provided in the illustrated machine, one of which is constrained to oscillate in unison with the inner knife and the other of which is constrained to oscillate 35 in unison with the outer knife, each feed dog being adapted to feed upon its forward stroke. The feed dogs of the illustrated machine, accordingly, move simultaneously in opposite directions, the length of stroke of each feed dog being equal 40 to that of the knives so that each channel is produced by successive cuts the length of each of which is equal to the length of the knife stroke plus the length of the feed stroke, as in the case 45 of the machine of the above-mentioned Ballard Patent No. 1,623,225.

50 In the use of sole fitting or channeling machines, as well understood by those skilled in the art, it is necessary for the operator manually and rapidly to turn or swing the sole approximately 180° in its own plane as the toe of the sole reaches the cutting means, in order that the cutting shall proceed properly around the toe, this manual turning being referred to by the operator as "swinging the sole at the toe". 55

In order to facilitate this operation of swinging the sole at the toe, channeling machines have been provided heretofore with manually operable means for varying the rate of work feed while the machine is running, whereby the operator is enabled to slow down the speed of the sole during operations around the toe. In order further to facilitate proper swinging of the sole at the toe, another feature of the present invention comprises the provision, in a sole fitting machine having an inner knife and an outer knife for cutting respectively an inner and an outer channel in a sole, of means for relatively moving the knives to facilitate cutting of the work, and means operable while the machine is running for relatively adjusting the knives to vary their relative positions in the line of feed of the sole in a manner tending to allow greater freedom of movement of the sole, thereby to prevent overcutting of the inner knife and to insure the production of a margin or feather of uniform width by the outer knife. In the embodiment of the invention herein illustrated, this result is accomplished by shifting the range of movement of the inner knife in the direction of work feed and by shifting the range of movement of the outer knife in a direction opposite to that of the work feed. Thus, at the end of each knife stroke during the momentary pause in the feed of the work, the outer or edge knife and the chamfering knife and the edge gage (which move back and forth in unison with the edge knife) will be located in advance of the inner knife, i. e., in a position nearer to an operator facing the machine. The positions of the knives and the edge gage will then be most favorable to the swinging of the sole since the tip of the toe will not then be crowded against the chamfer knife and the edge gage and there will be no danger that the edge knife will cut into that portion of the sole which should constitute the between substance.

It will be observed from the foregoing that the illustrated machine has an inner knife and an outer knife and means for moving said knives to cause them to make, respectively, an inner and an outer marginal cut in a sole as the margin of the sole is fed past said knives; that these knives are relatively adjustable lengthwise of the direction of feed of the sole margin; and that means is provided for effecting such relative adjustment of the knives while the knives are moving. This organization constitutes another feature of the invention.

Other features of the invention relate to the provision of improved means for supporting the extreme edge portion of a sole in the locality which is being operated upon, this means, as illustrated, comprising an auxiliary work support which is mounted to oscillate about the axis of the rotary work table; to improved means for moving the edge gage in synchronism with the movements of the channeling knives to facilitate the feeding of the sole in a manner tending automatically to turn the sole as required to present all portions of its curved margin properly to the action of the knives; to improved means, illustrated as slashing knives carried by the feed dogs, for cutting into the surface at the grain side of a sole in a manner to facilitate the raising of the channel lips of insoles for welt shoes or, in the case of soles which are to be attached to shoes by means of adhesive, to prepare such soles for the reception of the adhesive; and to improvements in the driving mechanism and general organization of the machine as a result

of which a machine has been produced which will run with unusual smoothness and quietness at high speed and in which vibration and wear has been reduced to a minimum, these results being obtained in the illustrated machine partly by the entire elimination of cam motions in the driving mechanism, the operative movements of the cutting and feeding instrumentalities being derived, as herein shown, from two eccentrics carried by a single vertically disposed main shaft. 10

The invention further resides in features of construction and combinations and arrangements of parts hereinafter described and claimed, the advantages of which will be apparent to those skilled in the art from the following description. 15

The invention will be described with reference to the accompanying drawings, in which

10 Fig. 23 is a left-hand side elevation of the lip and trimming knives shown in Fig. 22;

15 Fig. 24 is a fragmentary view in front elevation showing particularly the feed dogs and the knives in operation upon an insole;

20 Fig. 24a is a view showing a modified form of the feed dogs;

25 Fig. 25 is a sectional view taken substantially along the line XXXV—XXXV of Fig. 24;

30 Fig. 26 is a view similar to Fig. 18 but showing the machine fitted for operation upon a sole for a turn shoe;

35 Fig. 27 is a side elevational view;

40 Fig. 28 is a sectional view of a portion of an "Economy" insole as it appears after having been operated upon by the machine;

45 Fig. 29 is a view similar to Fig. 24 but illustrating the use of lip-slashing knives upon the feed dogs;

50 Fig. 30 is a view showing the channel and edge knives employed when the machine is fitted for turn work and illustrating the mode of operation of these knives upon a sole;

55 Fig. 31 is a sectional view of a portion of a sole for a turn shoe; and

60 Fig. 32 is a cross-sectional view illustrating particularly the relative positions of the knives and the feed dogs when the knife carriers are in mid-stroke positions.

The machine shown in the drawings comprises a freely rotatable flat work table or support 40, a channeling knife 42 for cutting downwardly into the surface of a sole S on the work table to form a channel and an inner lip, an edge knife 44 for slitting the edge of the sole to form an outer lip and a feather, presser gages 46 and 48 (Figs. 20 and 21) associated with the knives 42 and 44, respectively, for gaging the thickness of the inner and outer lips, two four-motion feed dogs 50 and 52 for feeding the work, and an edge gage 54 for determining the width of the feather and the position of the lips relatively to the sole edge. For convenience of description the expression "channeling knife" will be employed hereinafter to designate selectively the channeling knife 42 and the edge slitting knife 44. The illustrated machine, as fitted for channeling insoles for welt shoes may be provided, in addition to the above-mentioned channeling knives, with a dividing knife 58 (Figs. 22 and 23) for cutting, in the sole face, a vertical slit intersecting the edge slit and thus forming an outer lip which is narrower than the feather. The illustrated machine is also provided with a chamfering knife 60 (Fig. 12) for chamfering or beveling the marginal edge at the lower or grain side of the sole for a purpose well known in the art. The illustrated machine is adapted for use in making soles for turn shoes, as well as for welt shoes, and for that purpose certain operative parts of the machine are interchangeable with corresponding parts of a modified construction adapted particularly for turn work.

65 The channeling knives 42 and 44 are moved back and forth in the line of work feed and are arranged to cut on their backward strokes, the knives moving simultaneously in opposite directions so as to 70 cut in alteration and thus to divide the cutting

strain and distribute it evenly over the entire period of operation upon the work. The feed dogs 50 and 52 move back and forth in the line of feed in unison with the movement of the knives 42 and 44 respectively, the feed dog 50 advancing the work while the edge knife 44 is moving backwardly to cut the work and while the channel knife 42 is moving idly forward with the work, and the feed dog 52 advancing the work while the channeling knife 42 is moving backwardly to cut the work and while the edge knife 44 is moving idly forward with the work, this arrangement insuring that the length of the cut made by each knife will be equal to the distance traveled by that knife plus the distance traveled by the work during the cutting operation.

75 The back-and-forth movements are imparted to the knives and the feed dogs by mechanism comprising two carriers 62 and 64 (Fig. 11) which are mounted to oscillate about vertical axes 10-20 located at opposite sides of the line of work feed, the carriers being connected to swing simultaneously in opposite directions and being moved by a two-arm lever 66 which is oscillated by means of an eccentric 68 on a vertical driving shaft 70. 25 The feed dogs 50 and 52 are raised and lowered relatively to the carriers 62 and 64 while the carriers are being oscillated by means of mechanism actuated by a second eccentric 72 on the shaft 70. The shaft 70 is journaled in bearings in a frame 30 comprising a head 74 upon which the operating parts of the machine are mounted, a hollow standard 76 which supports the head 74, and a base 78 upon which is mounted a motor 80 that is connected to drive the shaft 70 and is covered by 35 means of a hood 82. The operation of the motor is controlled by a suitable switch 84 and rheostat 86.

80 As a result of the oscillatory movement of the feed dogs 50 and 52 derived from the oscillatory carriers 62 and 64, combined with the up-and-down movements of the feed dogs derived from the eccentric 72, each feed dog has a four-way motion enabling it to operate intermittently on the work. The feed dog 52, for example, after 45 being lowered into engagement with a sole on the table 40 is moved forwardly by means of the carrier 64 to advance the sole one step, while the inner knife 42 is moved backwardly a like amount to make a short cut which is to form part of an 50 inner channel in the sole. The feed dog then rises to release the work and is moved idly toward its starting position by the backward stroke of the carrier 64, while the inner knife 42 is moved idly forward by the forward stroke of the carrier 55 62. During this forward or non-cutting stroke of the inner knife 42 the feed dog 50 which is mounted on the same oscillatory carrier as the knife 42 imparts another feed movement to the sole, advancing the sole in unison with the forward 60 movement of the inner knife so that when that knife is again ready to cut the relation of its cutting edge to the work will be the same as at the end of the preceding cutting stroke or, in other words, it will still be located at the forward 65 extremity of the cut. Thus, the knife can again cut throughout the entire length of its stroke while the work is being fed in the opposite direction by the feed dog 52 a distance equal to the length of the stroke of the knife. The feed dog 70 52 may therefore be considered to be a main feeding means and the feed dog 50 to be an auxiliary feeding means so far as the operation of the inner channeling knife 42 is concerned. Considering the operation of the feed dogs with 75

reference to the outer knife 44, the feed dog 50 functions as a main feeding means to advance the sole during the backward cutting stroke of the outer knife 44, while the feed dog 52 functions as an auxiliary feeding means to advance the sole during the idle forward stroke of the outer knife. Inasmuch as the back-and-forth movements of the two carriers 62 and 64 are equal, the length of the movements imparted to the work by the feed dogs 50 and 52 is the same as the length of the cutting strokes of the knives. As a result of this arrangement and by reason of the auxiliary feed movements above described, the present machine is enabled at each successive cutting operation to produce a cut which is approximately twice the length of the knife stroke and which is approximately twice as long as the distance traveled by the work while that cut is being made. Moreover, inasmuch as successive cuts are made at opposite sides of the line of work feed, one cut being in the inner channel and the next cut being in the outer channel, the cutting strain is divided and distributed evenly throughout the entire period of operation upon the work. In addition, the draw cutting action of the knives resulting from the oscillatory movements of the carriers 62 and 64 makes it easier for the knives to cut and consequently less power is required to feed the sole against the knives and cleaner cuts will be produced.

The driving connections between the motor 30 and the shaft 70 comprise a horizontal shaft 90 (Figs. 1 and 2) which is arranged in end-to-end relation to the motor shaft 92 and is connected with the latter by a coupling 94 and has secured thereto a gear 96; a pinion 98 which is secured upon a horizontal shaft 100 and is driven by the gear 96; a gear 102 which is secured to the shaft 100 and drives a pinion 104 (Fig. 2) that is fast upon a horizontal shaft 106; and a gear 108 which is secured upon the shaft 106 and drives a gear 110 that is secured to the shaft 70 by means of a key 112, as best shown in Fig. 2. The shafts 99, 100 and 106 are journaled in bearings formed in the walls of a casing 114 which encloses and protects the driving gear. The casing 114, together with the enclosed driving gearing, is mounted with provision for vertical setting up adjustment relatively to the main shaft 70 for the purpose of bringing the shaft 99 into alignment with the motor shaft 92. To this end, the casing 114 is supported upon a hollow post 116 the lower end of which is secured, by means of a clamp screw 118, within a split sleeve 120 formed in the bottom of the pedestal 76. When the clamp screw 118 is loosened to permit vertical adjustment of the casing 114 with the enclosed gearing, the weight of the casing is borne by means of a screw 122 which is threaded in the bottom of the pedestal 76 and is adapted to be turned by a wrench to effect a fine adjustment of the elevation of the casing 114 and the driving gearing.

The main shaft 70 is journaled at its upper portion within ball bearings 124 (Fig. 7) mounted in the head 74 and at its lower portion within ball bearings 126 (Fig. 2) mounted in the adjustable gear casing 114, while the weight of the shaft 70 is supported by means of a thrust bearing 128 (Fig. 7) which is supported within the head 74. The gear 110 has formed integrally therewith a sleeve 130 which extends upwardly within a bearing 132 in the gear casing 114 and is formed with an internal diameter somewhat greater than the diameter of the shaft 70 to prevent cramping 75 of the shaft due to any inaccuracy in alinement

of the shaft bearings and insure that the shaft will turn freely. The upper end of the sleeve 130 extends beyond the shaft bearing and has fixed thereto a collar 138 which engages the top of the casing 114. A thrust bearing 146 is provided between the gear 110 and the lower end of the bearing 132. A hand wheel 142 on the main shaft 70 enables the machine to be conveniently turned over by hand when it is desired.

The oscillatory carriers 62 and 64 upon which the channeling knives and the feed dogs are mounted each comprise two vertically spaced arms 150 and 152 (Fig. 7) which extend from the top and bottom, respectively, of each carrier. The carrier arms 150 and 152 are fixedly secured to the upper and lower ends, respectively, of two vertical rockshafts 156 and 158 (Figs. 11 and 17) the middle portions of which are journaled in bearings 160 and 162 formed in the head 74. As best shown in Figs. 10 and 11, the two carriers 62 and 64 are constrained to oscillate simultaneously in opposite directions by means comprising a link 166 the opposite ends of which are connected to rearwardly extending arms 168 on the carriers 62 and 64, and a link 170 which connects the arm 168 of the carrier 64 with one arm of the eccentric-operated two-arm lever 66. The two-arm lever 66 has formed integrally therewith a depending stud 172 which is mounted to turn in a vertical bearing in the head 74. The forwardly extending arm of the lever 66 is forked, as best shown in Fig. 11, to receive a slide block 174 through which the eccentric 72 extends. The rearwardly extending arm of the lever 66 is slotted, as indicated at 176, to receive a roll 178 carried by one end of the link 170. As shown, the outer portion of the slot 176 is curved about the pivotal connection of the link 170 with the carrier arm 168 as a center, while the inner portion of the slot 176 is curved in an arc eccentric to the pivotal connection above referred to. Through the above-described connections, not only may the carriers 62 and 64 be oscillated simultaneously in opposite directions, as hereinbefore set forth, but by shifting the link 170, by means of operator-controlled connections comprising a link 180 and other means hereinafter to be described, the roll 178 may be moved inwardly or outwardly in the slot 176 to vary the amplitude of the oscillations imparted to the carriers 62 and 64. The slot 176 is extended inwardly sufficiently to enable the roll 178 to be adjusted into coaxial relation with the axis of oscillation of the lever 66 and thereby to render the movement of that lever ineffective to oscillate the carriers 62 and 64 so that no cutting movement will be imparted to either of the knives and no feeding movement will be imparted to either of the feed dogs. The above construction enables the feed strokes of the feed dogs to be shortened to facilitate feeding of a sole during operations around the toe and even to be nullified if it should be desired to stop the feed of the work at any time without stopping the machine. The curvature of the eccentric inner portion of the slot 176 is such that after the feed stroke has been shortened a predetermined amount by shifting the roll 178 to the inner end of the concentric part of the slot 176, further inward movement of the roll 178 will result, not only in further shortening of the length of the feed stroke, but also in relatively displacing the ranges of movement of the inner and outer knives in a manner to facilitate the swinging of the sole at the toe, as will be more fully explained hereinafter.

The inner channeling knife 42 and the presser gage 46 associated therewith are mounted upon a slide 186 (Fig. 17) which is capable of yielding vertically in the oscillatory carrier 62. The outer channeling knife 44 and its presser gage 48 are mounted upon a slide 188 arranged for vertical yielding movement in the carrier 64. The depth to which the inner channeling knife is permitted to penetrate the work and the location of the cut produced by the outer channeling knife relatively to the upper surface of the work are determined by the presser gages 46 and 48, respectively, in a customary manner.

The inner or channeling knife 42 comprises a rectangular, vertically disposed shank portion 190 (Fig. 17) having formed at its lower extremity a cutting edge 192 adapted to cut inwardly from the face of a sole to form an inner channel A and a channel lip B in a sole such as the sole shown at C in various figures of the drawings. At its upper end the shank portion of the channeling knife 42 is rigidly secured by means of a screw 194 within a groove 196 in a knife block 198. The knife block 198 is mounted with provision for horizontal sliding adjustment transversely with respect to the direction of work feed within a groove 200 in a carrier 202 by means of a bolt 204 which extends through a horizontally elongated slot 206 (Fig. 17) in the carrier 202 and is threaded into the knife block 198. The knife block 202 is rigidly secured to the lower portion of the channeling knife slide 186 by means of a bolt 208 which extends through a vertically elongated slot 210 in the carrier 202. The presser gage 46, associated with the channeling knife 42, is formed upon a carrier plate 212 (Fig. 18) which is fixedly secured to the front of the channeling knife slide 186 by means of a screw 214. The channeling knife 42 may be adjusted vertically relatively to the presser gage to vary the depth of its cut in the work by loosening the bolt 208 and adjusting the channeling knife block carrier 202 vertically upon the slide 186. For the purpose of securing a fine adjustment of the depth of cut produced by the channeling knife, an adjustment screw 216 is provided, the screw having a shank portion threaded into the channeling knife block carrier 202, and a knurled head which engages within a notch 218 (Fig. 20) in the back of the knife slide 186. A binding screw 220 is provided for locking the screw 216 in adjusted position.

The knife slide 186 is mounted for vertical sliding movement within a slideway 222 (see also Fig. 14) in the oscillatory carrier 62. The slide 186 is adapted to yield upwardly against the action of the coiled spring 224 which is housed within a bore in the upper portion of the slide, the upper end of the spring bearing against a follower 226 which is engaged by a screw 228 that is threaded through a bracket 230 secured to the oscillatory carrier 62. Downward movement of the knife slide 186 under the influence of the spring 224 is limited by engagement of stop lugs 232 (Figs. 7 and 18) with shoulders 234 on the carrier 62. The stop lugs 232 are formed at opposite extremities of a crossbar 236 which is secured to the slide 186. The stop lugs 232 serve to prevent the knife 42 from engaging the surface of the work table 40 when the work is removed from beneath the presser gages. The tension of the spring 224 may be varied by adjustment of the screw 228. A suitable check nut 238 on the screw 228 serves to lock the latter in adjusted position. The slide 186 is retained

within its slideway 222 by means of a casting 240 (Figs. 9, 14 and 17) which is secured to the carrier by screws 242, and within which is formed a vertical guideway for a slide, hereinafter referred to, which carries the feed dog 50.

The outer or edge knife 44 has a horizontally disposed cutting edge 246 (Figs. 22 and 23) for slitting the edge of an insole, such as an insole for a welt shoe, to form an outer slit or channel D, an outer channel lip E and a feather F. As best shown in Figs. 17, 19 and 21 to 23, the shank portion of the edge knife 44 rests upon the bottom of a recess 248 in a knife holder 250 with one lateral edge portion engaging an undercut shoulder 252 on the holder 250 and the opposite lateral edge of the edge knife shank being engaged by the inner ends of two screws 254 which are tightened to clamp the knife in the holder. As shown, the bottom of the recess 248 is inclined to the horizontal to afford the desired rake or clearance for the knife. Because of the shortness of the strokes of the knives more rake may thus be provided for the edge knife than is usually practicable without causing the knife to have any undue tendency to "dig in". For the same reason the inner channeling knife 42 may be "backed off" more than is customarily considered practicable without causing that knife to "dig in". By loosening the clamp screws 254 the edge knife may be readily adjusted lengthwise of its cutting edge to vary the width of the edge slit. The edge knife holder 250 is formed with an upstanding portion 256 having flanges 258 which engage opposite sides of the edge knife slide 188 and the knife holder 250 is rigidly secured to the slide 188 by means of a screw 260, the latter extending through a vertically elongated slot 262 in the knife holder 250 so as to permit vertical adjustment of the knife holder relatively to the slide 188 for the purpose of varying the thickness of the edge lip and feather. For the purpose of effecting a fine vertical adjustment of the edge knife relatively to its presser gage, an adjusting screw 264 is threaded through the upper portion of the knife holder 250, the screw having a knurled head which engages within a notch 266 in the knife slide 188 and the screw 264 being retained in adjusted position by means of a binding screw 268.

The edge knife slide 188 is mounted for vertical movement within a slideway 270 in the oscillatory edge knife carrier 64 in a manner similar to that in which the channel knife slide 186 is mounted in the channel knife carrier 62. As shown, the edge knife slide 188 is adapted to yield upwardly against the action of a coiled spring 272 which is housed within a bore in the slide 188 and bears at its upper end against a follower 274 which is engaged by a screw 276 which may be turned to vary the tension of the spring, the latter being threaded through a bracket 278 on the carrier 64 and being provided with a lock nut 280. Downward movement of the edge knife slide 188 under the influence of the spring 272 is limited by engagement of stop lugs 282 carried by the slide 188 with shoulders 284 formed upon the carrier 64. The stop lugs 282 are formed at the opposite extremities of a crossbar 286 which is secured to the slide 188 and they serve to prevent the edge knife 44 from engaging the surface of the work table when the work is removed from the machine. The edge knife slide 188 is retained within its slideway 270 by means of a casting 288 (Figs. 9, 14 and 17) which is secured to the carrier 64 by screws 289.

and within which is formed a vertical guideway for a slide, hereinafter referred to, which carries the feed dog 52.

- It is sometimes desirable, for example, in the manufacture of so-called "Economy" insoles, to form an outer lip which is narrower than the feather. For this purpose the dividing knife 58 is employed to slit the face of the sole along a line parallel to the sole edge and to cooperate with the edge knife in forming the narrow lip E by severing a chip G from the margin of the sole. In order to facilitate the passage of the dividing knife 58 and the edge knife 44 through the work and thus to insure the making of cleaner cuts by each of said knives the dividing knife is arranged to cut at a point substantially in advance of the edge knife. This relative arrangement of the dividing knife and the edge knife have been found to be particularly advantageous in cutting manufactured insoles composed of stock containing latex or similar material which is less easily cut than leather. It has also been found that by slitting downwardly from the face of the sole at a point in advance of the cutting edge of the edge knife it is easier to swing the sole when operating around the toe. The illustrated dividing knife (Figs. 22 and 23) is formed with a cutting edge 290 and with an upwardly extending shank portion which is rigidly secured by means of a screw 292 to a block 294 having a dovetailed connection with a lug 296 on the side of the edge knife holder 250. As shown, the shank of the dividing knife 58 is received in a shallow recess in the block 294, the recess having edge walls 295 which are inclined so as to position the dividing knife with its cutting edge 290 sloping upwardly and rearwardly from its lowermost or operative extremity thereby further facilitating clean cutting by causing the knife to cut with a drawing action. The screw 292 extends through a slot 298 in the block 294, the slot being extended in a direction parallel to the cutting edge of the dividing knife. The construction and mounting of the dividing knife is therefore such that after the cutting edge of the knife has been resharpened and the lower extremity of the knife has been ground back so as to shorten the knife somewhat, the lead of the dividing knife over the edge knife may be maintained by adjustment of the knife in the direction of the length of its cutting edge. The dividing knife block 294 is secured to the lug 296 by means of a thumb screw 300 which is threaded into the block and extends through a horizontal slot 302 in the lug 296. This arrangement permits adjustment of the dividing knife in a direction lengthwise of the cutting edge of the edge knife to vary the width of the outer lip E. The edge knife presser gage 48 is rigidly secured by a screw 305 to an auxiliary slide 306 which is mounted within a vertical slideway 308 in the edge knife slide 188, and provision is made whereby the auxiliary slide 306 may be fixedly secured to the main slide 188 to adapt the machine for operating upon insoles for welt shoes and may be disconnected from the main slide so that it will be capable of moving independently thereof to adapt the machine for operating upon soles for turn shoes. As shown, the auxiliary slide 306 is bored, as shown at 309 in Fig. 26, to receive a coiled spring 310 the upper end of which bears against a shoulder 312 on the edge knife slide 188, and a pin 314 carried by the auxiliary slide 306 is adapted to cooperate with the ends of a slot

316 in the edge knife carrier 64 to limit the upward and downward movement of the auxiliary slide. A screw 318 (Fig. 24) threaded through the carrier 64 is adapted to engage within an aperture 320 (Fig. 26) in the auxiliary slide 306 for the purpose of fixedly connecting the auxiliary slide to the main slide 188. By removing the screw 318, or turning it sufficiently to withdraw its extremity from the aperture 320, the auxiliary slide may be released from the main slide so that it can yield vertically independently of the latter.

When operating upon welt work it is essential to insure that the outer lip shall be maintained of uniform thickness irrespective of any variation in the thickness of the sole. By utilizing the screw 318 fixedly to secure the auxiliary slide 306 to the edge knife slide 188 the presser gage 48 and the edge knife 44 will be connected for yielding movement in unison. Consequently, the edge knife will rise or fall with the presser gage 20 in response to variation in work thickness so as to maintain uniformity in the thickness of the lip. In turn work, on the other hand, it is essential that the thickness of the feather shall be maintained uniform regardless of variation in the sole 25 thickness. This result will be insured by removing or loosening the screw 318, thereby enabling the spring 310 to hold the edge knife at the level determined by engagement of the pin 314 with the bottom of the slot 316 and adapting 30 the presser gage 48 (which is carried by the auxiliary slide 306) to yield upwardly in response to the variation in work thickness without carrying the edge knife with it. Thus, the edge knife will be maintained at a fixed level relatively to 35 the surface of the work table so as to insure uniformity in the thickness of the feather.

As shown in Fig. 17 the feed dogs 50 and 52 are carried by slides 324 (each comprising an inner spindle 336 and an outer sleeve 338) and the 40 slides 324 are guided for up-and-down movements within slideways formed in the castings 240 and 288 which serve also to retain the knife carrier slides within their respective guideways in the oscillating knife carriers 62 and 64. Each feed 45 dog is formed with a toothed lower surface for engagement with the work and with an upwardly extending shank portion which is secured to a feed dog holder 326 by means of a screw 328 which extends through a vertically elongated slot 50 330 in the holder 326 and is threaded into the shank of the feed dog, the slot permitting vertical adjustment of the feed dog relatively to its holder. Each feed dog is prevented from turning about its attaching screw 328 as a pivot by 55 means of flanges 332 formed on the holders 326 between which the shanks of the feed dogs extend. The upper ends of the feed dog shanks bear against the heads of screws 233 (Figs. 20 and 21) which are threaded into the holders 326 60 and serve to receive the thrust on the feed dogs when the latter are pressed downwardly against the work. The screws 233 may be turned by means of their knurled heads to assist in adjusting the feed dogs vertically with respect to 65 their holders to vary their action upon the work. As shown in Fig. 29, the feed dogs may carry knives 334 having horizontal cutting edges which not only assist in feeding the work but constitute means for cutting into the upper surface 70 of the sole at right angles to the sole edge to form incisions or slits H (Figs. 29 and 30) in advance of the channeling knives, the incisions being formed to such a depth that, when the lips or flaps have been formed by the channeling knives, 75

they will be divided or slit transversely as shown in Fig. 30 so that they may be more easily raised to form the sewing rib. Such slitting of the channel lips is particularly advantageous where the lips are to be raised into positions substantially normal to the face of the sole as in so-called "Economy" insoles of the type shown in Fig. 28. The slitting knives 334, of course, serve also as means for feeding the work and the adjacent work-engaging faces of the feed dogs may be toothed, as shown at 51 on the feed dog 50 in Fig. 29, or they may be smooth, as shown at 51x on the feed dog 52x in Fig. 24a, in which latter case the slitting knives alone will be relied upon to secure feeding engagement between the feed dogs and the work and the smooth lower faces 51x of the feed dogs will function to limit the depth to which the slitting knives are permitted to penetrate the work.

20 The feed dogs 50 and 52, being mounted upon the oscillatory carriers 62 and 64 upon which the channeling knives are also mounted, are moved in arcuate paths corresponding to the paths of movement of the knives. The inside feed dog 50, being movable about an axis located at the left of the line of work feed, moves in a counterclockwise direction, viewed from above, during its feeding stroke and consequently tends to turn the sole a very slight amount in a counterclockwise direction. Inasmuch as it is necessary for the sole to be turned in a counterclockwise direction as it is being fed in order that the edge of the sole shall be held against the edge gage, it will be seen that the movement of the inside feed dog actually tends to maintain the edge of the sole in contact with the edge gage. The outside feed dog 52 moves in a clockwise direction during its feeding stroke but it nevertheless tends to swing the sole in a counterclockwise direction since it tends to cause the sole to pivot about the point of the inside channel knife. The edge gage, which oscillates about the axis of the work table, also has some tendency, during its forward stroke, to assist in turning the sole counterclockwise, the tendency being made more effective as a result of the fact, hereinafter more fully explained, that the axis of the work table is offset rearwardly relatively to the axes of oscillation of the knife carriers 62 and 64. Thus, both feed dogs impart to the sole a distinct tendency to turn in a counterclockwise direction so that, except at the toe or other sharply curved portions of the sole margin, it is often unnecessary for the operator manually to guide the sole in order to hold it against the edge gage.

60 The feed dog holders 326 are formed integral with the lower ends of the spindles 336, the upper reduced portions of which are arranged to telescope within sleeves 338 which, together with the spindles, constitute the feed dog slides. Each sleeve 338 is formed with a counterbored recess for receiving a coiled spring 340 which encircles the respective spindle 336, the lower end of the spring engaging a washer 342 seated against the shoulder on the spindle, while the upper end of the spring is seated against the top of the counterbored recess in the sleeve. The force of the spring 340 tends to urge the spindle downwardly relatively to the sleeve and maintain the spindle with its feed dog in a vertical position determined by engagement of a crosspin 344 in the spindle with the lower end of a vertical groove 346 in the sleeve 338. The 70 spring is adapted to be compressed by continued

downward movement of the sleeve 338 after the feed dog has engaged the work on the table, thus adapting the feed dog, without special adjustment, to accommodate soles of different thicknesses and also insuring that the teeth of the feed dogs will embed themselves deeply enough into the work to secure positive feeding engagement therewith. The feed member of each feed dog slide is provided at its upper end with an upstanding ear 348 which is connected by a ball-and-socket joint 349 with the lower end of a link 350 the upper portion of which is connected by a ball-and-socket joint 352 with a rocker member 354 which is fixedly secured to a horizontal stud 356. The opposite ends of the stud 356 are fixedly secured within two uprights 358 that are bolted to the head 74. The ball-and-socket joints 349 and 352 permit the links 350 to accommodate both the vertical swinging movements of the rocker member 354 and the horizontal oscillatory movements of the channeling knife carriers 62 and 64. The above-described arrangement of an eccentric-operated actuator, indirectly connected by means of the links 350 with the feed dog slides, provides for a substantial pause or dwell between successive feed movements imparted to the work and allows ample time, between the feed impulses, for manual swinging of the sole. On the other hand, while the feeding mechanism is intermittent in its action, the work is advanced faster than in most continuous feed machines because of the high speed at which it is practical to run the machine.

75 The above-described construction is such that as the rocker member 354 is oscillated, up-and-down movements will be imparted to the feed dog slides 324 through the links 350. The rocker member 354 is actuated from the eccentric 72 through connections comprising a stop motion mechanism 360, and including an actuator 362; the stop motion mechanism operating to disconnect the feed dogs from the mechanism which moves them up and down, in case the work should be removed from beneath the feed dogs at any time while the machine is running, and the work table is occupying its elevated position. This is to insure that the feed dogs will not be caused to strike against the table thereby injuring the table and causing unnecessary noise and vibration. The stop motion mechanism also acts to nullify the up-and-down movements of the feed dogs when the work table is lowered to insure against engagement of the feed dogs with the table in case the latter should be raised into operative position without having a sole thereon. The eccentric-operated actuator 362, from which the up-and-down movements of the feed dogs are derived, is located in front of the rocker member 354 and is mounted upon the fixed pivot stud 356 and it is adapted to be oscillated continuously while the machine is running by means of the eccentric 72 through connections comprising a rod 364 having a ball and socket joint connection 366 with the actuator and pivotally connected at 367 with an eccentric sleeve 368 on the eccentric 72. The actuator 362 is adapted to be maintained in operative connection with the rocker member 354 so long as the work is located upon the work table in position to be operated upon and to be disconnected from the rocker member so as to nullify the up-and-down movements of the feed dogs whenever the work is removed from beneath the presser gages 48 and 49.

The means for connecting the actuator 362 with the rocker member 354 comprises a finger 370 which is pivoted at 372 to the rocker member and which carries a coupling stud 374 which is adapted to enter a notch 376 in the actuator. A spring 377, connected at its upper end to the rocker member 354 and at its lower end to the finger 370, tends to hold the coupling stud 374 in engagement with the notch 376 so that the operative 10 driving connections may be maintained between the actuator 362 and the rocker member 354 so long as work is present beneath the knives. Upon the passage or removal of the work from beneath the knives, however, the driving connections 15 between the actuator 362 and the rocker member 354 are broken by means of a pawl 378 pivoted at 380 upon the head 74 and adapted to engage a shoulder 392 upon the finger 370, the pawl being acted upon by a spring 384 tending to 20 maintain the pawl in engagement with the shoulder 382. The pawl 378 is adapted to be drawn into position to engage the shoulder 382 and to cause the coupling stud 374 to be withdrawn from the notch 376 by connections with the channeling 25 knife slide 186, comprising a rod 386 which is slidably mounted within a central bore in the vertical rockshaft 156, and a bracket 388 which rigidly connects the lower end of the slide rod 386 with the channeling knife slide 186. The 30 upper extremity of the slide rod 386 projects above the rockshaft 156 and engages an extension 390 of the pawl 378. As hereinbefore explained, the channeling knife slide 186 is continuously urged downwardly by the action of the spring 35 224, the vertical position of the slide and of the channeling knife being determined by the presser gage 46 which rides along the surface of the sole. When the sole rides out from beneath the presser gage 46, or when the work table 40 is lowered, the 40 resulting downward movement of the slide 186 under the action of the spring 224 lowers the rod 386 and permits the spring 384 to raise the pawl 378 into the path of the shoulder 382 upon the finger 370 carried by the oscillating rocker member 354. When, during the movement of the 45 rocker member 354 toward the left, the shoulder 382 is brought into engagement with the pawl 378, the finger 370 will be brought downwardly to disengage the coupling stud 374 from the notch 376 in the actuator 362 to disconnect the latter from the rocker member 354. Upon disconnection of the rocker member 354 from the actuator 362 a spring-pressed plunger 392 mounted in one 50 of the uprights 358 acting upon a flattened surface 394 on the rocker member 354 serves to bring the rocker member into the central or neutral position in which it appears in Fig. 7 and in which position the two feed dog slides will be brought to rest each in a vertical midstroke position, i. e., in 55 a position halfway between the limits of the up-and-down movements of the feed dogs. Thus, not only will the feed dogs have no vertical movements imparted to them, but both the feed dogs will be maintained in positions clear of the work 60 table where they will not interfere with the insertion of a new piece of work. When a new piece of work is placed upon the feed table and beneath the presser gages 46 and 48, the upward movement of the channeling knife slide will be communicated, through the rod 386, to the pawl extension 390 and the pawl 378 will be disconnected from the shoulder 382, thus permitting the spring 377 to swing the extension 390 upwardly to engage the coupling stud 374 with the notch 376 75 and thus to reestablish driving connections be-

tween the actuator 362 and the rocker member 354.

In order to prevent the spring-pressed plunger 392 from acting upon the rocker member 354 while the latter is being oscillated and thus unnecessarily resisting the movement of the rocker member, the plunger 392 is adapted to be latched in retracted position by means of a hook-shaped pawl 396 (Fig. 6) pivoted at 398 to one of the uprights 358, the pawl 396 being adapted to engage a flange 10 400 on the plunger. For the purpose of releasing the pawl 396 from the flange 400 so that the plunger shall operate to bring the feed dogs into neutral position when no work is present in the machine, the pawl 396 is connected with the extension 390 on the pawl 378 by means of a rod 402 the upper end of which is pivoted at 404 to the pawl 396 and the lower end of which is adapted to slide through a block 406 pivotally connected to the extension 390. Movement of the pawl 20 extension 390 is yieldingly communicated to the rod 402 by means of a spring 408 surrounding the rod 402 between the block 406 and a collar 410 adjustably fixed on the rod 402. All of the above-described mechanism, as well as the operative 25 connections with the eccentrics on the main shaft 70, are covered and protected by means of a removable hood 411 shown in Figs. 1 and 7.

The work table 40 comprises a disk having a central cylindrical stem 412 (Fig. 7) which is 30 mounted to turn idly within a vertical bearing sleeve 414 which extends through a block 416 that supports the table. The work table rests upon ball bearings 418 carried by the block 416 which permit the table to turn freely as a sole is 35 advanced by the action of the feed dogs 50 and 52 and thus to impose only a minimum amount of frictional resistance to the movement of the sole. The work table supporting block 416 is fixedly secured to a horizontally adjustable carrier 420 40 which also supports the edge gage 54 and the chamfering knife 60 and which is movable to adjust the edge gage, the chamfering knife and the work table in unison transversely of the direction of work feed and thus to shift the sole edgewise 45 relatively to the channeling knives so as to vary the distance between the channels and the sole edge or, as commonly expressed, "to vary the width of the margin".

The edge gage 54 and the chamfering knife 60 50 are mounted upon an auxiliary work support 422 as best shown in Fig. 12. The auxiliary work support 422, together with the edge gage and the chamfering knife, is oscillated in a horizontal plane about the axis of the work table 40, the 55 forward and backward movements of the gage occurring in unison with the forward and backward strokes of the outer lip knife 44 in order that the edge gage shall be maintained at a uniform distance from that knife as the latter moves 60 back and forth and thus to insure against any undesired variation in the width of the sole margin such as might otherwise occur, for example, at the toe of a more or less pointed toe insole. The edge of the auxiliary oscillating 65 work support 422 which is adjacent to the work table 40 is curved to conform to the curvature of the edge of the table and is arranged close to the edge of the table so that, even though the auxiliary support moves back and forth relatively 70 to the table 40, there will be no gap opened up between these parts but a continuous surface will be afforded at all times for supporting the sole throughout the extent of the region being operated upon. Thus unyielding and adequate sup- 75

port is provided for the marginal chip which is cut from the lower face of the insole by the chamfering knife during the entire extent of the cutting stroke of that knife, thereby insuring that there will be no variation in the edge thickness of the feather due to uneven cutting of the chamfering knife and making it practicable to employ a chamfering knife shaped to bevel the sole edge at an unusually small angle to the face of the sole, for example, an angle of 15° or less, while still insuring clean cutting and uniformity of edge thickness reduction. The work table 40 is mounted with provision for accurate setting up adjustment relatively to the auxiliary work support 422 in order to provide for only sufficient clearance between the adjacent edges of the table and the auxiliary support to insure that the table will turn freely. For this purpose a rib 424, which is formed on the under side of the block 416, fits within a horizontal undercut or dovetailed guideway 426 in the carrier 420. The block 416 is fixedly but adjustably secured to the carrier 420 by means of a set screw 428 (Fig. 3) the inner end of which engages the rib 424 on the block 416. The work table carrier 420 is formed with a depending hollow stem 430 which is rotatably supported in the line of the pressure exerted upon the work by the feed dogs and the presser gages. As shown, the work table stem 430 is mounted in a vertical bearing 432 formed in the middle portion of an arm 434 the rear portion of which is fixedly secured by means of a nut 436 to the reduced upper end of a vertical rockshaft 438 which is journaled in a bracket 440 formed on the head 74.

To permit adjustment of the edge gage transversely of the direction of work feed to vary the width of the margin in different portions of the sole, provision is made for adjustment of the work table carrier supporting arm 434 about the vertical rockshaft 438. For this purpose, the forward end of the arm 434 is slotted to receive a block 442 (Figs. 3 and 6) carried by an eccentric pin 444 projecting from a disk 445 fixed to the upper end of a vertical rockshaft 446 and which is adapted to be manually turned to adjust the arm 434 and the work table, as will be hereinafter described. The carrier 420 is prevented from being displaced relatively to the carrier arm 434 by means of a post 448 (Fig. 7) secured to the head 74 and engaging between a pair of lugs which are formed on the lower side of the carrier 420 and one of which is shown at 450.

The work table carrier 420 is supported within the bearing 432 in the arm 434 by means of a nut 454 (Fig. 7) on the threaded upper portion of a post 456 which, in turn, is supported by two toggle links 458 and 460 (Fig. 3) of which the latter is pivoted at 462 between the ears of a bracket 464 which is secured by a clamp screw 466 to the lower end of the vertical rockshaft 438. The nut 454 is formed with an annular flange 468 on which rests the stem 430 of the work table carrier 420. For the purpose of turning the post 456 so as to raise or lower the nut 468, and thus to adjust the elevation of the work table 40 to adapt the machine for operating upon soles of different thicknesses, a hand wheel 470 is clamped by means of a nut 472 against a shoulder 474 on the post 456. A spring-pressed latch 476, pivoted at 477 to the exterior of the bearing 432, is adapted to engage with notches 478 formed in the periphery of the hand wheel 470 to hold the latter normally against turning and

thus to secure the table in vertically adjusted position. A series of suitable graduations upon the surface of the hand wheel 470 are adapted to co-operate with the latch 476 as a fixed reference point to indicate the adjustment of the table by means of figures indicating units or "irons" of sole thickness. For example, by turning the hand wheel 470 until the graduation marked 5 is opposite the latch 476, the work table will be adjusted vertically to adapt the machine to operate upon a sole of the thickness of 5 irons. The toggle links 458 and 460 are connected together by means of a knuckle pivot 480 while the toggle link 458 is connected with the post 456 by means of a ball-and-socket joint 482, the latter permitting rotation of the post 456 for the purpose of adjusting the elevation of the work table.

As shown in Fig. 3, the toggle comprising the links 458 and 460 is shown in a straightened condition determined by engagement of an extension 484 of the toggle link 460 with the lower portion of the bracket 464; a spring 486, secured at its upper end to the arm 434 and at its lower end to the toggle link extension 484, tends to maintain the toggle links straightened so as to support the work table 40 in work supporting position. In order that the work table 40 may be lowered to facilitate introduction or removal of the work, the toggle link extension 484 is connected by means of a rod 488 with a foot treadle 490 (Fig. 1) which is secured to a horizontal rockshaft 492 that is journaled in the base 78 of the machine. By depressing the treadle 490 the toggle link extension 484 may be swung in a direction to break the toggle 458—460 and thus to lower the work table. Upon release of the treadle 490, the spring 486 will cause the toggle 458—460 to straighten and thus to raise the work table into work supporting position. Inasmuch as the toggle is straightened when the treadle 490 is raised, the work table will be unyieldingly supported in its operative position.

As best shown in Figs. 3 and 6, the rockshaft 446 which is turned manually to adjust the carrier 420, with the work table and the edge gage, transversely of the direction of work feed to vary the width of the sole margin or, in other words, the distance between the channels and the edge of the sole, is journaled in a thimble 500 adjustably fixed in a bracket 502 formed on the head 74. The lower end of the rockshaft 446 carries a head 504 to which is pivotally connected, at 506, a hand lever 508 by which the rockshaft may be turned. When the rockshaft 446 is so turned the resulting movement of the eccentric pin 444 and the block 442 swings the arm 434, thereby moving the carrier 420, and with it the work table and the edge gage, transversely of the direction of work feed.

In channeling soles it is customary to use three different widths of margin, one at the shank portion, another at the inside of the forepart, and a third at the outside of the forepart and, accordingly, three adjustable stops are provided for determining the three operative positions of the edge gage. A pin 510, carried by the disk 445, extends into a recess 447 in the bracket 502 and is adapted to engage a shoulder 503 at one end of the recess 447 to limit the extreme forward position of the edge gage which the latter occupies when channeling with the narrowest margin. The intermediate position of the edge gage is determined by a latch 512 which is carried by the hand lever 508 and engages a recess 514 in a

- flange 516 on the lower end of the thimble 500. The position of the recess 514 may be adjusted by turning the thimble 500 and the thimble may be fixed in adjusted position by a clamp bolt 518 provided at its outer end with a lock nut 520. The latch 512 is held in engagement with the recess 514 by a spring 522 which tends normally to swing the hand lever 508 upwardly. By depressing the hand lever the operator releases the latch 512. The extreme rear position of the edge gage (which the latter occupies when channeling with the widest margin) is determined by a clamp collar 524 which is secured, by means of a clamp screw 525, upon the periphery of the disk 445 and is formed with a depending lug 526 which carries a pin 527 arranged to cooperate with a shoulder 528 on the bracket 502. This rearward position of the edge gage may be adjusted by loosening the clamp collar 524 and rotating it on the disk 445. To assist in adjusting the thimble 500 and the clamp collar 524 to vary the widths of sole margin which will be obtained when the hand lever 508 is shifted to position the edge gage for channeling with margins of intermediate and maximum widths, respectively, a pointer 530 (Fig. 6) is fixed on the head 74 and is arranged to cooperate with graduations on a scale 532 carried by the arm 434 which supports the work table.
- As shown in Fig. 12, the operative portion of the edge gage 54 rests upon the upper surface of the auxiliary table or sole margin support 422 and is formed with a smooth, vertical work-engaging face which is rounded to provide for a minimum amount of frictional resistance between the gage and the edge of the sole. The edge gage 54 has a depending shank portion 536 which is rigidly secured by means of a screw 538 to a rearwardly extending ear 540 on the auxiliary table 422. The screw 538 extends through a horizontal slot 542 in the ear 540 which permits adjustment of the edge gage relatively to the direction of work feed for the purpose of varying the width of the chamfer cut. As shown, a plate 544 which is interposed between the shank portion of the edge gage and the ear 540 and which is held in place by the screw 538 is formed with a horizontal rib 546 which is adapted to slide within a corresponding groove in the ear 540 to maintain the edge gage and the plate 544 in proper relation to the auxiliary table. The edge gage is maintained in fixed relation to the plate 544 by means of a rib 548 on the shank of the edge gage which fits within a corresponding recess in the plate 544.
- The chamfering knife 60 operates to chamfer or bevel the edge of the sole at the unchanneled or grain side, as indicated, for example, at J in Fig. 28, for a purpose well known in the art. As shown, the chamfering knife 60 is located closely adjacent to the edge gage 54, at the side which is foremost in the line of work feed, and the shank portion of the chamfering knife is located within a notch in the auxiliary table 422. The chamfering knife is rigidly secured to the auxiliary table 422 by means of a screw 550 which is threaded into the shank of the chamfering knife.
- As hereinbefore pointed out, the construction of the auxiliary table 422 and the chamfering knife 60 are such that although both the table and chamfering knife move back and forth in the line of work feed, the auxiliary table 422 affords a positive support for the extreme edge portion of

the sole at the point where the chamfer cut is being made at all times regardless of the position of the chamfering knife, thereby insuring clean cutting by the chamfering knife and maintaining uniform the thickness of the chamfered feather.

The auxiliary table 422 is supported by a post 554 to the top of which it is rigidly secured by means of a horizontal clamp bolt 556 (see also Fig. 12) and nut 558, the bolt being notched at its rear portion to receive the post 554 and the construction being such that when the nut 558 is tightened the bolt 556 will be drawn lengthwise into clamping engagement with the post. The post 554 is rigidly secured at its lower end to a flat lever 560 which rests upon the upper surface of the work table carrier 420 and carries, at its front end, a stud 562 which is mounted to turn in the bearing sleeve 414 in the work table supporting block 416, the construction being such that the axis of oscillation of the auxiliary support is coincident with the axis of rotation of the work table 40, so that the auxiliary support 422, which carries the edge gage and the chamfering knife, is mounted to oscillate about the axis of the work table 40. As illustrated clearly in Figs. 12 and 13, the axis *a* of the work table 40 is offset somewhat (rearwardly with regard to the direction of work feed) relatively to the common plane of the axes of oscillation of the knife carriers 62 and 64 (indicated at *b*) to insure that the edge gage, on its backward stroke, shall have no substantial component of movement toward the channeling knives tending to deflect the insole edgewise in a manner to interfere with the evenness of the channel cuts. As a result of this arrangement, also, the edge gage on its forward stroke will have a substantial component of movement toward the channeling knives and consequently, as hereinbefore pointed out, will tend to assist in imparting the desired counterclockwise turning movement to the sole as the latter is being fed.

For the purpose of oscillating the edge gage and the chamfering knife, the lever 560 is connected with the rockshaft 158 by means comprising a flat plate 564 which rests upon the lever 560 and is pivoted at its front end to the post 554, the plate 564 being located between the lever 560 and a rocker member 566 which is mounted with provision for vertical sliding movement upon the lower end of the rockshaft 158 and which is connected to turn with the rockshaft by means of a rearwardly offset post 568 on the rocker member 566, the post 568 extending upwardly between a pair of rearwardly projecting lugs 570 on the arm 152 of the carrier for the outer channeling knife. The rocker member 566 is provided with depending parallel flanges 572 (Figs. 10 and 13) which engage the opposite lateral edges of the plate 564 thereby causing the plate to oscillate with the rocker member while permitting relative sliding horizontal movement between the rocker member and the plate 564 as required to permit inward and outward adjustment of the work table carrier 420 and the edge gage. On account of the vertical sliding connection between the rocker member 566 and the rockshaft 158 and also between the post 568 and the lugs 570, the work table is enabled to be moved vertically toward and from normal work supporting position without interfering with the operative connections for oscillating the auxiliary work supporting table. A spring 574 surrounds the rockshaft 158 between the carrier arm 152 and the rocker member 566 and functions

yieldingly to maintain the rocker member in engagement with the lever 560.

After a sole has been channeled the work table 40 is lowered by depression of the foot treadle 490, as hereinbefore explained, to stop the feed of the work and to facilitate removal of the work from the machine. At the completion of a channeling operation on an insole for a welt shoe it is desirable that the channeling knives shall "cut out", i. e., that the knives shall cut upwardly through the sole material above the channel so as to emerge from the upper surface of the sole. To enable this result to be accomplished, provision is made whereby, upon depression of the foot treadle 490 to lower the work table 40, the channeling knives are raised before the table has been lowered sufficiently to stop the feed of the work. The arrangement is such, however, that by the time the knives have cut through the sole material and been raised clear of the work the work table will have been lowered far enough to relieve the compression of the feed dog springs 340 so that the feed dogs will no longer grip and feed the work. During the latter part of the downward movement of the foot treadle 490, and before the work table has reached its lowermost position, the channeling knife slides 186 and 188 are moved downwardly to position the knives in their lowermost positions, thereby to insure that after a new sole has been placed upon the lowered table and the table has been raised into operative position the upper face of the sole will be pressed upwardly against the knives so that the latter will be caused immediately to cut into and bury themselves within the material of the sole to a depth determined by the presser gages 46 and 48. To insure that the vertically vibrating feed dogs shall not repeatedly strike against the surface of the work table in case the table should be raised before a new sole has been placed upon it, or in case a sole which is being fed across the raised table should pass beyond the knives, the stop motion mechanism 360 is provided, as already explained, and functions to disconnect the rocker member 354 from the actuator 362 so that no more up-and-down movements will be imparted to the feed dogs and so that the plunger 250 may operate to bring the feed dogs to rest in vertical midstroke positions where they will not interfere with the insertion of a new sole. The downward movement of the inner knife slide 186 is made effective to operate the stop motion 360 for this purpose. The subsequent upward movement of the inner knife slide 186 caused by the engagement of the work with the channel knife presser gages when the work table is raised to start the feed of a new sole is made effective to operate the stop motion 360 to restore driving connections between the rocker member 354 and the actuator 362 to renew the up-and-down movements of the feed dogs and thus to start the feed of the new sole.

In the illustrated machine the initial raising and subsequent lowering of the channeling knife slides is effected during the downward movement of the work table by depression of the foot treadle 490 through the medium of the following mechanism. Two knife lifter arms 580 and 582 (Figs. 8, 9 and 10) are rigidly secured to a rockshaft 584 which is journaled in bearings in the head 74 and the lifter arms 580 and 582 are arranged to engage, respectively, one of the stop lugs 232 carried by the inner channeling knife slide 186 and one of the stop lugs 282 carried by the outer channeling knife slide 188 in such a manner that turning of the rock-shaft 584 in one direction will

raise the knife slides and turning of the rock-shaft in the opposite direction will permit the knife slides to be forced downwardly by the springs 224 and 272. The extent of movement of the lifter arms 580 and 582 is limited by means of stop screws 586 and 588 carried by a block 590 which is rigidly secured to the rock-shaft, the stop screws being arranged to engage with the surface of the head 74. The stop screws may be turned to vary the movements of the lifter arms to adapt the knives for operation upon welt work or upon turn work as may be required. Suitable lock nuts 592 are provided for holding the stop screws in adjusted positions. The rock-shaft 584 is provided with a rearward extension 585 (Fig. 5) upon which is rotatably mounted a clutch sleeve 594 having a downwardly extending arm 595. The arm 595 is connected by a pin-and-slot connection 596 with the upper arm of a bell crank lever 598 which is pivoted at 600 to the rear of the head 74. The other arm of the bell crank lever 598 is connected by a rod 602 with an arm 604 (Fig. 1) which is fixedly secured to the rock-shaft 492 which carries the foot treadle 490. A spring 603 surrounding the rod 602 urges the rod upwardly and tends to hold the treadle 490 in normal elevated position. The clutch sleeve 594 has a series of clutch teeth 606 formed in its rear end face which are adapted to cooperate with complementary clutch teeth formed in a second clutch sleeve 608 which is splined to the rearward extension 585 of the rockshaft 584. A spring 610, which encircles the rockshaft extension 585 between the clutch sleeve 608 and a collar 612 secured to the extension 585, normally holds the teeth of the clutch sleeves 594 and 608 in cooperative engagement. Upon depression of the foot treadle 490, the clutch comprising the members 594 and 608 operates to turn the rockshaft 584 in a direction to cause the lifter arms 580 and 582 to raise the knife slides 186 and 188 and thus to raise the inner and outer channeling knives. The lifter arms operate during the early part of the downward movement of the treadle to raise the knives before the table 40 has been lowered sufficiently to stop the feed of the work thereby insuring that the knives will cut through to the upper surface of the sole. After the knife slides have reached the limit of their upward movement as determined by the stop screws 588, further turning of the clutch sleeve 594, resulting from continued downward movement of the foot treadle 490, causes the spring 610 to yield to break the operative connection between the clutch sleeves, whereupon the springs 224 and 272 will depress the knife slides 186 and 188 to their lowermost positions so that the knives will be in readiness to operate upon a new sole. Downward movement of the inner knife slide 186 operates, through connections comprising the rod 386 and the pawl 318, to disconnect the actuator 362 from the rocker member 354 so that no further up-and-down movements will be imparted to the feed dogs. Upon disconnection of the rocker member 354 from the actuator 362 the plunger 392 will function to centralize the rocker member and thus to bring the feed dogs to rest at points midway between the upper and lower limits of their vertical movements in positions to facilitate the introduction of a new sole into the machine.

To adapt the machine for operating upon soles for turn shoes the outer channeling or edge knife 44 will be replaced by a shoulder knife, such as the knife 44a which is adapted to make a shoulder cut instead of an edge slit in the sole margin as 75

- illustrated in Fig. 31. In order that the thickness of the feather formed by the shoulder cut shall be maintained uniform regardless of variation in sole thickness, the screw 348 will be removed or disconnected from the knife holder 350, as hereinbefore explained, thereby enabling the presser gage 48 to yield upwardly in response to the variation in work thickness without carrying the edge or shoulder knife with it.
10. In many soles for turn shoes it is desirable that the edge or shoulder cut shall not extend into the heel portion of the sole although the cut made by the inner channeling knife is to continue around the heel. To adapt the machine to produce turn soles having these characteristics provision is made whereby the operator may raise the edge or shoulder knife without also raising the inner channeling knife. For this purpose the stop lug 292 carried by the outer knife slide 188 at the right-hand side of the machine is adapted to be engaged by means of a lifter arm 616 (Fig. 9) which is rigidly secured to a horizontal rockshaft 618 that is journaled in bearings in the head 74. A block 620 secured to the rockshaft 618 is provided with stop screws 622 and 624 for limiting the extent of upward and downward movements of the lifter arm. The stop screws 622 and 624 may be turned to adjust the movement of the lifter arm. Suitable lock nuts 626 are provided for securing the stop screws in adjusted position. The rockshaft 618 is provided with an extension 628 at the rear of the machine (see Figs. 5 and 8) to which is rigidly secured a downwardly extending arm 632. The arm 632 is connected by a pin-and-slot connection 634 with the upwardly extending arm of a bell crank lever 634 which is pivoted at 636 to the head 74. The opposite arm of the bell crank lever 634 is connected by a rod 638 with a foot treadle 640 (Fig. 1) which is fulcrumed upon the rockshaft 492. A spring 642 surrounds the treadle rod and tends to hold the treadle 640 in raised position. Upon depression of the treadle 640 the rockshaft 618 will be turned in a direction to swing the lifter arm 616 upwardly so as to raise the knife slide 188 and thus to lift the edge or shoulder knife clear of the work without also raising the inner channeling knife.
- For the purpose of varying the length of the feed strokes imparted to a sole while the sole is being fed through the machine and correspondingly varying the length of the knife strokes, the link 170, hereinbefore referred to, is connected by the link 180 (as best shown in Fig. 10) with the upper arm of a bell crank lever 646 (Fig. 9) which is fixedly secured to a rockshaft 648 that is journaled in bearings supported by the head 74 and which is adapted to be turned to swing the link 170 so as to move the cam roll 178 toward or from the axis of oscillation of the actuator arm 66. The extent of movement of the cam roll 178 toward the axis of the arm 66 is limited by means of a stop screw 650 carried by the bell crank lever 646 and arranged to engage the top of the head 74. The stop screw 650 may be adjusted to limit the extent to which the feed strokes may be reduced. A clamp screw 652 is provided for securing the stop screw 650 in adjusted position. If desired, the stop screw 650 may be adjusted to permit the cam roll 178 to be moved inwardly into coaxial alinement with the axis of the crank arm 66 so that no feed movements whatever will be imparted to the feed dogs. In this way the feed of the work may be arrested by the operator at any time during a

channeling operation without stopping the machine. Means for turning the rockshaft 648 comprises a lever 654 (Fig. 8) secured to the rear extremity of the rockshaft, a rod 656 connected with the lever 654, and a foot treadle 658 (Fig. 1) to which the rod 656 is connected, the treadle being mounted to turn upon the rockshaft 492. A spring 660 encircling the rod 656 tends to hold the foot treadle 658 in its raised position. In order that the feed dogs shall be adapted normally to impart feed strokes of maximum length to the work, the roller 176 is normally maintained yieldingly in an outer position in the cam groove 176. This result is accomplished by means of a spring 662 (Fig. 8) the force of which tends to rotate the rockshaft 648 in a direction counter to that in which it is turned by depression of the foot treadle 658, the extent of rotation of the rockshaft in that direction being determined by an adjustable abutment screw 664 carried by the lever 646 and arranged to engage the top of the head 74. As shown, the spring 662 encircles a rod 666 the upper end of which is pivoted at 668 to one extremity of the lever 654 and the lower end of which carries an adjustable abutment 670 for the spring. The spring is confined between the abutment 670 and a lug 672 through which the rod 666 is adapted to slide. If the inner portion of the cam slot in the lever which imparts the oscillatory movements to the knives 62 and 64 is made eccentric to the outer portion of the slot, as shown in the drawings, the shortening of the feed and knife strokes beyond the point where the roll enters the slot will automatically result in relatively displacing the ranges of movement of the oscillatory knife carriers 62 and 64 so as to advance or offset forwardly the outer or edge knife, the chamfer knife and the edge gage and to offset backwardly the inner or channeling knife to facilitate the swinging of the sole 40 at the toe and to avoid danger of the edge knife cutting too deep a slit in the sole. However, if the slot 176 is made concentric throughout its length with the pivotal connection of the link with the carrier 64 the knife and feed strokes 45 may be shortened without advancing the range of movement of the outer knife.

It has been found that by removing the channeling knives and employing feed dogs, such as those shown at 58x and 52x in Fig. 24a, with slitting knives 334x the machine may be adapted, by shortening the feed strokes, to operate upon soles, for example outsoles for cement process shoes, to form a series of closely adjacent incisions or indentations in their margins and thereby to prepare the soles in a very effective manner for the reception of an adhesive such as pyroxylin cement for securing the soles to the shoes. If desired, the knives 334x may be arranged, as shown in Fig. 24a, so that the incisions made by the outer knife will terminate somewhat short of the edge of the sole so as not to be visible in the finished shoe and so that adjacent incisions made by the two knives will be nearly or approximately continuous.

Upon depression of the foot treadle 658 the cam roll 178 will be moved inwardly in the cam slot 176 in the lever arm 66 so as to shorten the strokes of the feed dogs and the knives. If the treadle is depressed far enough to move the cam roll 178 into the eccentric inner portion of the cam slot 176, the range of movement of the carrier 62 will be displaced forwardly and the range of movement of the carrier 64 will be displaced rearwardly (relatively to the direction of 75

work feed) with the result that the strokes of the outer knife will be "advanced" relatively to the strokes of the inner knife as in Fig. 16 where in the lines *x* and *y* indicate, respectively, the locations of the cutting edges of the inner and outer channeling knives, at midstroke positions, when the ranges of movement of the knives have been offset substantially to the maximum amount provided for. In other words, the outer knife will be given a "lead" over the inner knife which will be maintained throughout the length of the knife strokes and which will materially facilitate the swinging of the sole inasmuch as it will relieve the cutting strain on the outer knife. This change in the relation of the ranges of movement of the inner and outer knives, coupled with the shortening of the knife strokes and the feed strokes, will make it practicable to channel around the toe of an extremely pointed toe insole without reducing the rate of rotation of the main shaft of the machine.

It is to be noted, however, that even if the ranges of movement of the inner and outer knives are not relatively offset by moving the cam roll 178 into the eccentric inner portion of the slot 176, the outer channeling knife will be advanced relatively to the inner channeling knife during the latter part of each cutting stroke of the outer knife, since the knives move simultaneously in opposite directions, and during that portion of the stroke of the outer knife, the knives will occupy relative positions which are most favorable to permit manual turning of the sole. In fact it has been found that most soles may be readily guided so as to keep their edges against the edge gage as they are being fed without depressing the treadle far enough to move the cam roll 178 into the eccentric portion of the slot 176 so as relatively to offset the ranges of movement of the inner and outer knives. Accordingly it may be found desirable, particularly if extremely pointed toe soles are not to be operated upon, to form the slot 176 in the lever 66 so that its inner portion, as well as its outer portion, is concentric with the pivotal connection of the link 170 with the carrier arm 168.

As a result of the oscillation of the carriers 62 and 64 about vertical axes located at opposite sides of the line of work feed the inner and outer knives, which are mounted upon these carriers, have each an arcuate path of movement, causing the knives to cut with a drawing action and tending to produce cleaner cutting. The feed dogs 50 and 52, being likewise mounted upon the oscillating carriers 62 and 64, are also moved through arcuate paths such that each feed dog acts upon the sole in a manner tending to keep it in contact with the edge gage, as hereinbefore explained. Moreover, the feed dog associated with one of the oscillating carriers feeds the work while the knife carried by the other carrier cuts the work. Consequently each knife will be caused to cut with a more pronounced drawing action since not only will the oscillatory movement of the knife produce a component of knife movement in a direction transverse to the general line of work feed, but the oscillatory movement of the feed dog which feeds the work against the knife will produce a component of work movement in a direction transverse to the general line of work feed and opposite to that of the transverse component of knife movement. Furthermore, the relative movements of the knives are such, except in

cases where the ranges of movement of the knives have been shifted by means of the treadle 553 to facilitate operations at the toe of a peaked-toe sole, as hereinbefore described, that the inner knife, at the end of each cutting stroke, will be located in advance of the outer knife, i. e., nearer to the operator than the outer knife, and the two knives will then be relatively positioned so as materially to facilitate the turning or swinging of the sole which, in the present 10 machine, is in a counterclockwise direction. The turning of the sole is facilitated under these conditions because the sole will pivot about the tip of the outer knife and the between substance will clear the heel of the inner knife instead of 15 being crowded against it, as would be the case if the inner knife were located rearwardly of the outer knife. Notwithstanding this, however, it is sometimes desirable when operating at the toe of a peaked-toe insole to shift the ranges of 20 movement of the knives, as already described, so as to position the outer knife in advance of the inner knife, since in operating around a pointed toe there is danger of the outer knife cutting too deep an edge slit if it is positioned 25 rearwardly of the inner knife and, furthermore, if the edge knife is so positioned the chamfer knife and the edge gage will offer greater resistance to the turning of the sole than would be offered by the heel of the inner knife. 30

To start the illustrated machine it is only necessary to throw the switch 86 to set the motor 88 in operation. If there is no work present upon the work table 40 to engage the presser gages 46 and 48, and thus to hold the channeling 35 knife slides elevated, no up-and-down movements will be imparted to the feed dogs and consequently, while the latter will move back and forth in a horizontal plane, they will not strike against the surface of the feed table, even 40 though the latter occupies its uppermost position. On account of the eccentric-operated driving mechanism for the operating instrumentalities the machine will run smoothly and substantially without vibration and noise at high 45 speed. To enable a sole to be introduced into the machine the work table may be lowered by depressing the treadle 490. Upon release of the treadle the work table will rise to its normal operative position, thereby raising the sole 50 against the channeling knives and lifting the inner channeling knife slide sufficiently to disengage the pawl 378 from the finger 370 and thereby to enable driving connections to be established between the rocker member 354 and the 55 actuator 362 so that up-and-down movements will be imparted to the feed dogs 50 and 52, thereby rendering the latter effective to feed the work. As the work begins to advance the knives will immediately cut in from the upper 60 surface of the sole and bury themselves in the work to a depth determined by the presser gages 46 and 48. In channeling insoles for welt shoes it is usual to start the channeling operation at the rear of the shank portion in one lateral margin of a sole and to stop the channeling operation at a corresponding location in the opposite lateral margin of the sole. The channeling operation may be stopped at any desired point by depression of the foot treadle 490 which results 65 in raising the channeling knives and lowering the work table. The table, however, is lowered slowly enough to insure that the feed dogs will continue to feed the work until after the knives have cut through the sole material to a position 70 75

clear of the work. As a sole is being fed the hand lever 508 may be manipulated, if desired, to vary the distance between the channel cuts and the edge of the sole at different localities 5 around the sole. As the channeling operation proceeds to a location near the toe of the sole the treadle 658 may be depressed for the purpose of shortening feed strokes of the knives and the feed dogs and thereby facilitating the manual 10 swinging of the sole. If the two-arm lever 66 is provided, as in the illustrated machine, with a slot 176 having an eccentric inner portion, the ranges of movement of the inner and outer channeling knives will be relatively offset, automatically, as the length of the strokes of the channeling knives are shortened and, through connections between the carrier for the outer channeling knife and the auxiliary work support 422, 15 the range of movement of the edge gage and the 20 chamfering knife will likewise be offset relatively to that of the inner channeling knife, thereby further facilitating the manual swinging of the sole at the toe.

In operating upon soles for turn shoes the 25 machine is ordinarily equipped with a shoulder knife, such as the knife 44a, in place of the edge slitting knife. In the case of soles for turn shoes having sewed heel seats the channeling operation, which is commenced at the rear of the 30 shank portion at one side of the sole, is continued at the opposite side of the sole rearwardly around the heel-seat portion to a point forward of where the knife originally cut in to the sole. To stop the channeling and permit removal of the sole from the machine the treadle 35 498 is depressed to lower the work table and raise the knives and at the same time the sole is pulled rearwardly by the operator to disengage it from the inner channeling knife. The heel 40 of the inner knife will then leave the channel through the entrance slit cut by the knife at the beginning of the channeling operation. In the case of soles for turn shoes having nailed heel seats where it is undesirable to have the 45 shoulder cut extend around the heel portion of the sole, the outer or shoulder knife may be raised independently of the inner knife, when the channeling has progressed to the desired point, by depressing the treadle 640.

50 Having described my invention, what I claim as new and desire to secure by Letters Patent of the United States is:

1. In a sole fitting machine, in combination, 55 an oscillatory knife movable about an axis intersecting the plane of a sole being fed to the knife and located at one side of the line of feed of the sole, a second oscillatory knife movable about an axis located at the opposite side of said line of feed, the knives being adapted to cut each with a drawing action on its backward stroke, and means for feeding the sole against each knife while the knife is moving backwardly to cut the sole and for feeding the sole with each knife during the forward or non-cutting stroke of the knife.

2. In a sole fitting machine, in combination, 60 an oscillatory knife movable about an axis intersecting the plane of a sole being fed to the knife and located at one side of the line of feed of the sole, a second oscillatory knife movable about an axis located at the opposite side of said line of feed, the knives being adapted to cut each with a drawing action on its backward stroke, means for feeding the sole against each knife while the knife is moving backwardly to

cut the sole, and other means for feeding the sole with each knife during the forward or non-cutting stroke of the knife.

3. In a sole fitting machine, in combination, a knife moving backwardly and forwardly in the line of feed of the work and arranged to cut upon its backward stroke, means for feeding the work against the knife while the knife is moving backwardly, and means for feeding the work with the knife during the forward movement of the knife, said knife and said first-named feeding means each having components of movement transverse to the general direction of work feed and disposed to cause the knife to cut with a drawing action.

4. In a sole fitting machine, in combination, means for supporting a sole, reciprocatory means for feeding the sole over said support, and an oscillatory knife movable about an axis intersecting the plane of the sole and located at one side of the line of feed of the sole, the knife cutting with a drawing action on its backward stroke during the forward movement of the reciprocating feeding means and said feeding means being constructed and arranged to impart to the sole a component of movement in a direction lengthwise of the cutting edge of the knife to increase the drawing action of the knife in cutting the sole.

5. In a sole fitting machine, in combination, an oscillatory knife effective on its backward stroke to cut a sole with a drawing action, and an oscillatory feed device effective upon its forward stroke to advance the sole to the knife while imparting to the sole a component of movement lengthwise of the cutting edge of the knife to increase the drawing action of the knife upon the sole.

6. In a sole fitting machine, in combination, an oscillatory knife movable about an axis intersecting the plane of a sole being operated upon and located at one side of the line of feed of the sole, an oscillatory feed device movable about an axis intersecting the plane of the sole at the opposite side of the line of feed, and a second oscillatory knife movable about the axis of said feed device.

7. In a sole fitting machine, in combination, means for supporting a sole, a feed device movable about an axis intersecting the plane of the sole and located at one side of the line of feed of the sole and arranged to feed upon its forward stroke, and an oscillatory knife movable about an axis intersecting the plane of the sole and located at the opposite side of the line of feed and adapted to cut with a drawing action on its backward stroke during the forward movement of said feed device.

8. In a sole fitting machine, in combination, means for supporting a sole, a feed device movable about an axis intersecting the plane of the sole and located at one side of the line of feed of the sole and arranged to feed upon its forward stroke, an oscillatory knife movable about an axis intersecting the plane of the sole and located at the opposite side of the line of feed and adapted to cut with a drawing action on its backward stroke during the forward movement of said feed device, and means for feeding the sole during the forward stroke of said knife.

9. In a sole fitting machine, in combination, a work support, inner and outer knives mounted to oscillate in the planes of their cutting edges and in the line of feed of a sole on the work support, said knives being arranged to cut while moving in

- the same direction, means for moving said knives simultaneously in opposite directions to cause them to cut in alternation, and feed members mounted to oscillate in unison with said knives for feeding the work.
5. 10. In a sole fitting machine, in combination, a work support, two oscillatory carriers movable simultaneously in opposite directions about parallel axes located at opposite sides of the line of feed of a sole on the work support, a feed member on one of said carriers operable during movement of said carrier in one direction to feed the sole, and a knife on the other carrier operable during movement of said carrier in the opposite direction to cut the sole while the sole is being fed.
10. 15. 11. In a sole fitting machine, in combination, a work support, an oscillatory work feeding member movable about an axis normal to the face of a sole on the work support and located at one side of the line of feed of the sole, an oscillatory knife movable about an axis normal to the face of the sole and located at the opposite side of the line of sole feed, and means for moving said feed member in one direction to feed the sole and for simultaneously moving the knife in the opposite direction to cut the sole as the sole is being fed.
20. 25. 12. In a sole fitting machine, in combination, a work support, an inner channeling knife, an outer channeling knife, a carrier for said inner knife mounted to oscillate about an axis normal to the face of a sole on said support and spaced inwardly from said knife, a carrier for said outer knife mounted to oscillate about an axis normal to the face of the sole and spaced outwardly from said knife, and means for oscillating said carriers to cause each knife to cut with a drawing action, said means being constructed and arranged to cause said knives to be located one in advance of the other at the end of each oscillation of each of said carriers.
30. 35. 40. 13. In a sole fitting machine, in combination, a work support, an inner channeling knife, an outer channeling knife, a carrier for said inner knife mounted to oscillate about an axis normal to the face of a sole on said support and spaced inwardly from said knife, a carrier for said outer knife mounted to oscillate about an axis normal to the face of the sole and spaced outwardly from said knife, means movable in unison with each knife for feeding the sole while the other knife is cutting the sole, and means for oscillating said carriers to cause each knife to cut with a drawing action, said means being constructed and arranged to cause said inner knife to be normally located in advance of said outer knife at the end of each cutting stroke of said inner knife so as to facilitate turning of the sole.
45. 50. 55. 14. In a sole fitting machine, in combination, a work support, two carriers mounted to oscillate in a plane parallel to the face of a sole on the work support, a knife on one of said carriers for cutting an inner channel in a sole, a knife on the other of said carriers for cutting an outer channel in a sole, means on each of said carriers for feeding the sole, and means for moving said carriers simultaneously in opposite directions to cause said knives and said feeding means to act in alternation to cut and feed the sole.
60. 65. 70. 75. 15. In a sole fitting machine, in combination, a work support, two carriers mounted to oscillate in a plane parallel to the face of a sole on the work support, a knife on one of said carriers for cutting an inner channel in a sole, a knife on the other of said carriers for cutting an outer channel in a sole, means on each of said carriers for feeding the sole, and means for moving said carriers simultaneously in opposite directions to cause said knives and said feeding means to act in alternation to cut and feed the sole, and means for feeding the sole, means for moving said carriers simultaneously in opposite directions to cause said knives and said feeding means to act in alternation to cut and feed the sole, and means for controlling the extent of oscillation of said carriers.
75. 16. In a sole fitting machine, in combination, a channeling knife arranged to reciprocate in a plane parallel to the face of a sole being operated upon, means for operating the knife to cut with a drawing action upon its backward stroke, and means for feeding a sole against the knife in a direction to increase the drawing action of the knife while the knife is moving backwardly and for feeding the sole with the knife during the forward stroke of the knife.
10. 15. 20. 25. 17. In a sole fitting machine, in combination, a channeling knife and an edge slitting knife arranged to oscillate about different axes and to move simultaneously in opposite directions in a plane parallel to the face of a sole being operated upon and to cut upon their backward strokes, a feed device for advancing the sole during the backward stroke of one of the knives, and a second feed device for advancing the sole during the forward stroke of said knife.
30. 35. 18. In a sole fitting machine, in combination, intermittently operative feed means movable in an arcuate path about an axis perpendicular to the face of a sole being operated upon to advance the sole, means movable in a different arcuate path in said plane and in a direction opposite to the direction of feed to cut the sole while the sole is being advanced by said feed means, and an auxiliary feed device for advancing the sole while said feed means is inoperative.
40. 45. 50. 55. 19. In a sole fitting machine, in combination, a feed device movable back and forth about an axis located at one side of the line of work feed and intermittently operative to advance a sole, a knife mounted to oscillate about an axis located at the opposite side of the line of work feed, said knife being movable backwardly in a plane parallel to the face of the sole to cut the sole with a drawing action while the sole is being advanced by said feed mechanism and being movable forwardly while said feed mechanism is inoperative to advance the work, and an auxiliary feed device movable about the axis of movement of said knife for advancing the work with the knife during the forward or non-cutting stroke of the knife.
60. 65. 70. 75. 20. In a sole fitting machine, in combination, a work support, two carriers mounted to oscillate in a plane parallel to the face of a sole on the work support, a knife on one of said carriers for cutting an inner channel in a sole, a knife on the other of said carriers for cutting an outer channel in a sole, means on each of said carriers for feeding the sole, and means for moving said carriers simultaneously in opposite directions to cause said knives and said feeding means to act in alternation to cut and feed the sole.
65. 70. 75. 21. In a sole fitting machine, in combination, a work support, two carriers mounted to oscillate in a plane parallel to the face of a sole on the work support, a knife on one of said carriers for cutting an inner channel in a sole, a knife on the other of said carriers for cutting an outer channel in a sole, means on each of said carriers for feeding the sole, means for moving said carriers simultaneously in opposite directions to cause said knives and said feeding means to act in alternation to cut and feed the sole, and means for controlling the extent of oscillation of said carriers.

- for controlling the extent of oscillation of said carriers.
22. In a sole fitting machine, in combination, an oscillatory knife movable about an axis located at one side of the line of feed of a sole being operated upon, and an oscillatory edge gage movable about an axis located at the opposite side of the line of work feed.
23. In a sole fitting machine, in combination, 10 an oscillatory knife movable about an axis located at one side of the line of feed of a sole being operated upon, and an oscillatory chamfering knife movable about an axis located at the opposite side of the line of work feed.
- 15 24. In a sole fitting machine, in combination, an oscillatory knife movable about an axis located at one side of the line of feed of a sole being operated upon, an oscillatory edge gage movable about an axis located at the opposite side 15 of the line of work feed, and a chamfering knife movable in unison with said edge gage.
25. In a sole fitting machine, in combination, inner and outer knives mounted to oscillate in the plane of a sole being operated upon and about 20 axes located at opposite sides of the line of feed of the sole, and an edge gage mounted to oscillate in the plane of the sole and connected to move back and forth in timed relation with the back-and-forth movements of the knives.
- 30 26. In a sole fitting machine, in combination, an oscillatory inner channeling knife, an oscillatory outer channeling knife, means for moving said knives simultaneously in opposite directions to channel a sole, and an oscillatory edge gage connected to move back and forth in unison with the back-and-forth movements of said outer channeling knife.
27. In a sole fitting machine, in combination, inner and outer channeling knives mounted to 40 oscillate in the plane of a sole being operated upon and about parallel axes located at opposite sides of the line of feed of the sole, and an edge gage mounted to oscillate in the plane of the sole about an axis offset from the plane of the axes of oscillation of the channeling knives.
28. In a sole fitting machine, in combination, a rotary work supporting table, means for feeding a sole across the table, means for channeling the sole as it is being fed, an auxiliary sole support mounted to oscillate about the axis of the work table, and an edge gage carried by said auxiliary support.
29. In a sole fitting machine, in combination, a 50 rotary work supporting table, an auxiliary sole support mounted to oscillate about the axis of the work table and having a curved inner edge conforming to the curvature of the edge of the work table, and a chamfering knife carried by said auxiliary work support.
30. In a sole fitting machine, in combination, inner and outer channeling knives mounted to 55 oscillate about vertical axes located at opposite sides of the line of feed of a sole being operated upon, a rotary work supporting table having its axis offset rearwardly with respect to the direction of work feed relatively to the common plane of the axes of oscillation of said knives, an auxiliary work support mounted to oscillate about the axis of the work table, and an edge gage and a chamfering knife carried by said auxiliary work support.
31. In a channeling machine, in combination, a work support, two oscillatory carriers movable simultaneously in opposite directions about 60 parallel axes located at opposite sides of the line of feed of a sole on the work support, a feed member on one of said carriers operable during movement of said carrier in one direction to feed the sole, and a chamfering knife connected with the other carrier and operable during movement of said carrier in the opposite direction to cut the sole while the sole is being fed. 5
32. In a sole fitting machine, in combination, a work support, means for feeding the margin of a sole over said support, an inner channeling 10 knife mounted to oscillate about an axis normal to the face of the sole and spaced inwardly with respect to the line of feed of the sole margin, an outer channeling knife mounted to oscillate about an axis normal to the face of the sole and spaced outwardly with respect to the line of feed of the sole margin, an edge gage mounted to oscillate about an axis normal to the face of the sole and spaced inwardly with respect to said line of feed, and means for oscillating the 15 knives and the edge gage.
33. In a sole fitting machine, in combination, a rotary work supporting table, means for feeding the margin of a sole over said table, an inner channeling knife mounted to oscillate about an axis normal to the face of the sole and spaced inwardly with respect to the line of feed of the sole margin, an edge slitting knife mounted to oscillate about an axis normal to the face of the sole and spaced outwardly with respect to said 20 line of feed, a chamfering knife mounted to oscillate about the axis of the work table, connections between the chamfering knife and the edge slitting knife for constraining said knives to move back and forth simultaneously, and means for oscillating said knives. 25
34. In a sole fitting machine, in combination, inner and outer channeling knives mounted to oscillate about axes located at opposite sides of the line of feed of a sole being operated upon, a 30 chamfering knife mounted to oscillate about an axis located at the same side of the line of feed as said inner knife but offset relatively to the common plane of the axes of oscillation of said channeling knives, and means for oscillating said knives. 40
35. In a sole fitting machine, in combination, inner and outer channeling knives mounted to oscillate about axes located at opposite sides of the line of feed of a sole being operated upon, an edge 45 gage mounted to oscillate about an axis located at the same side of the line of feed as said inner knife but offset relatively to the common plane of the axes of oscillation of said channeling knives, and means for oscillating said knives and said edge gage. 50
36. In a sole fitting machine, in combination, a support for a sole, a reciprocating knife for cutting an inner channel in a sole, a reciprocating knife for cutting an outer channel in a sole, and means for relatively adjusting the ranges of movement of said knives in a direction to facilitate the swinging of a sole at the toe as the sole is being fed to advance its margin past said knives. 60
37. In a sole fitting machine, in combination, a support for a sole, a reciprocating knife for cutting an inner channel in a sole, a reciprocating knife for cutting an outer channel in a sole, and manually-controlled means operable while the machine is running for relatively adjusting the ranges of movement of said knives in a direction to facilitate the swinging of a sole at the toe as the sole is being fed to advance its margin past said knives. 65
38. In a sole fitting machine having an inner 70 75

knife and an outer knife for cutting respectively an inner and an outer channel in a sole, means for relatively moving the knives to cut the work, and means operable while the machine is running for relatively adjusting the knives to vary their relative positions in the line of feed of the sole.

5 39. In a sole fitting machine, in combination, an inner knife and an outer knife and means for moving said knives to cause them to make respectively an inner and an outer marginal cut in a sole as the margin of the sole is fed past the knives, said knives being relatively adjustable lengthwise of the direction of feed of the sole margin, and means for effecting such relative adjustment of said knives while the knives are moving.

10 40. In a sole fitting machine, in combination, an inner knife and an outer knife for making respectively an inner and an outer marginal cut in a sole as the sole margin is being fed past the knives, and means operable while the knives are cutting for relatively adjusting said knives lengthwise of the direction of feed of the sole margin to vary the relative positions of the knives at different portions of the sole margin.

15 41. In a sole fitting machine, in combination, means for supporting and feeding a sole, an inner knife for cutting an inner channel in a sole, an outer knife for cutting an outer channel in a sole, said outer knife being adjustable relatively to said inner knife lengthwise with respect to the line of work feed, and means for adjusting the outer knife to vary its position relatively to the inner knife at different portions of the margin of the sole being operated upon.

20 42. In a sole fitting machine, in combination, means for supporting and feeding a sole, an inner knife and an outer knife for cutting respectively an inner and an outer channel in the sole, the outer knife being adjustable into a position in advance of the inner knife, and means for adjusting the outer knife to vary its lead over the inner knife.

25 43. In a sole fitting machine, in combination, means for supporting and feeding a sole, an inner knife and an outer knife for forming respectively an inner and an outer channel in a sole, means for reciprocating said knives in the line of work feed, and means for varying the length of stroke of said knives and for correspondingly varying the relative positions of said knives lengthwise with respect to the line of work feed.

30 44. In a sole fitting machine, in combination, a support for a sole, an inner knife and an outer knife for cutting respectively an inner and an outer channel in the sole, a feed member, and means for reciprocating said knives and said feed member, and means for varying the length of stroke of said knives and said feed member and for correspondingly varying the relative positions of said knives lengthwise of the line of work feed.

35 45. In a sole fitting machine, in combination, means for supporting and feeding a sole, an inner knife for cutting an inner channel in the sole, an outer knife for cutting an outer channel in the sole, means for reciprocating said knives, and means for shortening the strokes of said knives and correspondingly advancing the outer knife relatively to the inner knife to facilitate swinging of the sole.

40 46. In a sole fitting machine, in combination, a support for a sole, a reciprocatory knife for cutting an inner channel in a sole, a reciprocatory knife for cutting an outer channel in a sole, an edge gage reciprocable with the outer channeling knife for guiding the sole as the sole is be-

ing fed to advance its margin past said knives, and means for effecting relative adjustment between the range of movement of the inner channeling knife and the range of movement of the outer channeling knife and the edge gage to facilitate the swinging of a sole at the toe. 5

47. In a sole fitting machine, in combination, a support for a sole, a reciprocatory knife for cutting an inner channel in a sole, a reciprocatory knife for cutting an outer channel in a sole, and means for shortening the strokes of said knives and simultaneously relatively adjusting the ranges of movement of the knives in a direction to facilitate swinging of a sole at the toe. 10

48. In a sole fitting machine, in combination, a support for a sole, a reciprocatory knife for cutting an inner channel in a sole, a reciprocatory knife for cutting an outer channel in a sole, and means for adjusting the outer channeling knife forwardly relatively to the inner channeling knife 20 to facilitate the swinging of a sole at the toe.

49. In a sole fitting machine, in combination, a support for a sole, a reciprocatory knife for cutting an inner channel in a sole, a reciprocatory knife for cutting an outer channel in a sole, and means for adjusting the inner channeling knife backwardly and for adjusting the outer channeling knife forwardly to facilitate the swinging of the sole at the toe. 25

50. In a sole fitting machine, in combination, a support for a sole, a reciprocatory knife for cutting an inner channel in a sole, a reciprocatory knife for cutting an outer channel in a sole, an edge gage reciprocable with the outer channeling knife, and means for adjusting the outer channeling knife and the edge gage forwardly relatively to the inner channeling knife to facilitate the swinging of the sole at the toe. 30

51. In a sole fitting machine, in combination, a support for a sole, a reciprocatory knife for cutting an inner channel in a sole, a reciprocatory knife for cutting an outer channel in a sole, an edge gage reciprocable with the outer channeling knife, and means for adjusting the inner channeling knife backwardly and for adjusting 45 the outer channeling knife and the edge gage forwardly to facilitate the swinging of the sole at the toe. 40

52. In a sole fitting machine, in combination, a support for a sole, a reciprocatory knife for cutting an inner channel in a sole, a reciprocatory knife for cutting an outer channel in a sole, an edge gage reciprocable with the outer channeling knife, and means for shortening the strokes of both knives and for simultaneously adjusting 55 the inner channeling knife backwardly and the outer channeling knife and the edge gage forwardly to facilitate the swinging of the sole at the toe.

53. In a sole fitting machine, in combination, a support for a sole, a reciprocatory knife for cutting an inner channel in a sole, a reciprocatory knife for cutting an outer channel in a sole, an edge gage reciprocable with the outer channeling knife, and means for adjusting the range of 60 movement of the inner channeling knife backwardly and the ranges of movement of the outer channeling knife and the edge gage forwardly to facilitate the swinging of the sole at the toe. 65

54. In a sole fitting machine, in combination, 70 a work support, an edge knife arranged to reciprocate in the plane of a sole on said support to cut inwardly from the edge of the sole, an edge gage arranged to engage the sole edge at a point in advance of the edge knife to guide the sole as it 75

- is being fed, connections between the edge gage and the edge knife for reciprocating the edge gage in unison with the edge knife, and means for adjusting the range of movement of both the edge knife and the edge gage to favor feeding of the sole past the edge gage while the edge knife is operating upon the toe portion of the sole.
55. A channeling machine comprising a work support, an edge knife arranged to reciprocate in the plane of a sole on said support to cut inwardly from the edge of the sole, an edge gage arranged to engage the sole edge at a point in advance of the edge knife to guide the sole as it is being fed, connections between the edge gage and the edge knife for reciprocating the edge gage in unison with the edge knife, and means for varying the length of stroke of both the edge knife and the edge gage and simultaneously shifting forwardly the range of movement of the edge gage to facilitate swinging of the sole at the toe.
56. A channeling machine comprising a work support, a channeling knife arranged to reciprocate in the plane of the sole on said support to cut an inner channel in the sole, an edge knife arranged to reciprocate in the plane of the sole to cut an outer channel in the sole, an edge gage for guiding the sole as it is fed over the support, connections between the edge knife and the edge gage for reciprocating the edge gage in unison with the edge knife, and means for effecting relative adjustment between the range of movement of the channeling knife and the range of movement of the edge knife and the edge gage to favor swinging of the sole at the toe.
57. A channeling machine comprising a work support, a channeling knife arranged to reciprocate in the plane of the sole on said support to cut an inner channel in the sole, an edge knife arranged to reciprocate in the plane of the sole to cut an outer channel in the sole, an edge gage for guiding the sole as it is fed over the support, connections between the edge knife and the edge gage for reciprocating the edge gage in unison with the edge knife, and means for offsetting forwardly the range of movement of the edge knife and the edge gage relatively to the range of movement of the channeling knife to give the edge knife a lead over the channeling knife and to shift the edge gage forwardly and thereby to position the edge knife and the edge gage relatively to the channeling knife to favor swinging of the sole at the toe.
58. A channeling machine comprising a work support, a channeling knife arranged to reciprocate in the plane of the sole on said support to cut an inner channel in the sole, an edge knife arranged to reciprocate in the plane of the sole to cut an outer channel in the sole, an edge gage for guiding the sole as it is fed over the support, connections between the edge knife and the edge gage for reciprocating the edge gage in unison with the edge knife, and means for shortening the lengths of strokes of the channeling knife, the edge knife and the edge gage and for shifting rearwardly the range of movement of the channeling knife and shifting forwardly the ranges of movement of the edge knife and the edge gage.
59. A channeling machine comprising a support for a sole, a channeling knife arranged to reciprocate in the plane of a sole on said support to cut a channel in the sole, an edge gage for guiding the sole as it is fed over said support to move the sole margin past the channeling knife, and

means for adjusting the range of movement of the channeling knife relatively to the edge gage to facilitate swinging of the sole to move the toe of the sole past the edge gage.

60. A channeling machine comprising a support for a sole, a channeling knife arranged to reciprocate in the plane of a sole on said support to cut a channel in the sole, an edge gage arranged to engage the sole edge at a point in advance of the region acted upon by said knife to guide the sole as it is fed over said support, and means for shifting the range of movement of said knife in a direction away from the edge gage to facilitate the passage of the toe of the sole past the edge gage.

61. A channeling machine comprising a support for a sole, a channeling knife arranged to reciprocate in the plane of a sole on said support to cut an inner channel in the sole, an edge knife arranged to reciprocate in the plane of the sole to cut an outer channel in the sole, an edge gage for guiding the sole as it is fed over said support, and means for adjusting the ranges of movement of both knives to facilitate the swinging of the sole while the toe of the sole is being operated upon by the knives.

62. A channeling machine comprising a support for a sole, a channeling knife arranged to reciprocate in the plane of a sole on said support to cut an inner channel in the sole, an edge knife arranged to reciprocate in the plane of the sole to cut an outer channel in the sole, an edge gage arranged to engage the sole edge at a point in advance of the region acted upon by said knives to guide the sole as it is being fed, and means for shifting the range of movement of the channeling knife in a direction away from the edge gage and for shifting the range of movement of the edge knife in a direction toward the edge gage to facilitate the swinging of the sole while the toe portion of the sole is being operated upon by the knives.

63. A channeling machine comprising a work support, a channeling knife adapted to reciprocate in the plane of a sole on said support to cut a channel in the sole, an edge gage for guiding the sole as it is fed over said support, and means for varying the length of stroke of the knife and for simultaneously shifting the range of movement relatively to the edge gage to facilitate swinging of the sole while the toe of the sole is being operated upon by the knife.

64. A channeling machine comprising two oscillatory carriers, a channeling knife and a feeding device mounted on each carrier, mechanisms for moving said carriers simultaneously in opposite directions to cause said knives and feeding devices to cut and feed the work in alternation, and means for manually controlling the extent of oscillation of both of said carriers.

65. A channeling machine comprising a work support, a channeling knife arranged to reciprocate in the plane of a sole on said support to cut a channel in the sole, an edge knife arranged to reciprocate in the plane of the sole to cut an outer channel in the sole, an edge gage for guiding the sole as it is fed over the work support, and means for shifting the range of movement of each of said knives relatively to the edge gage and for simultaneously varying the length of stroke of each of said knives to facilitate swinging of the sole during the operation of said knives upon the toe portion of the sole.

66. A channeling machine comprising a work support, a channeling knife arranged to recipro-

cate in the plane of a sole on said support to cut an inner channel in the sole, an edge knife arranged to reciprocate in the plane of the sole to cut an outer channel in the sole, an edge gage for guiding the sole as it is fed over the work support, and means for shifting the channeling knife away from the edge gage and for shifting the edge knife toward the edge gage and for simultaneously shortening the length of stroke 5 of the channeling knife and the edge knife to facilitate swinging of the sole during the operation of said knives upon the toe portion of the sole.

67. A channeling machine comprising a work support, a channeling knife arranged to reciprocate in the plane of a sole on said support to cut an inner channel in the sole, an edge knife arranged to reciprocate in the plane of the sole to cut an outer channel in the sole, an edge gage for guiding the sole as it is fed over the work support, and means for shortening the length of stroke of the channeling knife and the edge knife, said means being operative after the lengths of said knife strokes have been shortened a predetermined amount to shift the ranges of movement of said knives in directions away from each other to facilitate swinging of the sole while said knives are operating upon the toe portion of the sole.

68. In a channeling machine, a channeling knife, an oscillatory carrier for the channeling knife, a link pivoted at one end to said carrier and having a stud at its opposite end, a two-arm lever having an arcuate slot extending lengthwise of one of its arms into which said stud extends, said slot having a portion concentric with the pivotal axis of said link and a portion eccentric to said pivotal axis, a shaft, operative connections between said shaft and the other arm of said lever for oscillating the lever, and manually-controlled means for adjusting said link to locate said stud in said slot in different locations to vary the extent of reciprocation imparted to said carrier and to vary the length of stroke imparted to said carrier.

69. In a sole fitting machine, a feed dog having a four-way motion for feeding the work, means for moving the feed dog back and forth in the line of work feed, means for moving the feed dog toward and from the work, and means rendered effective by removal of the work from the machine for rendering said last-named means inoperative.

70. In a sole fitting machine, a work table capable of being raised and lowered, a feed dog having a four-way motion for feeding the work, means for moving the feed dog back and forth in the line of work feed, normally ineffective means for moving the feed dog toward and from the work, and means rendered effective by the presence of a sole on the work table when the latter is in its raised position for rendering said last-named means operative.

71. In a sole fitting machine, a feed dog having a four-way motion for feeding the work, means for moving the feed dog back and forth in the line of work feed, means for moving the feed dog toward and from the work, and means rendered effective by removal of the work from the machine for rendering said last-named means inoperative and for stopping the feed dog in a position midway between the extremities of its movements toward and from the work.

72. In a sole fitting machine, a feed dog having a four-way motion for feeding the work,

means for moving the feed dog back and forth in the line of work feed, a continuously oscillating actuator, mechanism adapted to be driven by said actuator for moving the feed dog toward and from the work, normally inoperative coupling 5 means connecting said actuator and said mechanism, and means rendered effective by the introduction of a sole into the machine for rendering said coupling means operative.

73. In a sole fitting machine, a work support, 10 sole fitting means, a feed member having a four-way motion for feeding a sole on the work support to the fitting means, means for moving the feed member back and forth in the line of work feed, a continuously operating actuator, an ac- 15 tuator mechanism adapted to be driven by said actuator for moving the feed member toward and from the work, coupling means connecting said actuator with said mechanism, a latch for holding the coupling means inoperative, and means 20 operated by engagement with a sole on the work support for throwing out the latch.

74. In a sole fitting machine, a work support, sole fitting means, a feed member having a four-way motion for feeding a sole on the work support to the fitting means, means for moving the feed member back and forth in the line of work feed, an actuator mechanism adapted to be driven by said actuator for moving the feed member toward and from the work, coupling means 25 connecting said actuator with said mechanism, a pawl for holding the coupling means inoperative, means operated by engagement with a sole on the work support for throwing said pawl out of operative position, a spring for returning said 30 pawl into operative position, and means rendered operative upon the return movement of said pawl for moving the feed member into a position midway between the ends of its strokes toward and from the work.

75. In a sole fitting machine, a work support movable between a lowered position and a raised position, sole fitting means, a feed member having a four-way motion for feeding a sole on the work support to the fitting means, means for moving 45 the feed member back and forth in the line of work feed, a continuously oscillated actuator, a rocker member, connections between the rocker member and feed member for moving the latter toward and from the work, a coupling device for 50 connecting the actuator with the rocker member, a latch for holding the coupling device inoperative, and means rendered operative by the presence of a sole on the work support when the latter is in its raised position for throwing out the 55 latch.

76. In a sole fitting machine, a work support movable between a lowered and a raised position, a channeling knife, a feed dog having a four-way motion for feeding a sole on the work support to 60 the channeling knife, means for moving the feed dog back and forth in the line of work feed, a continuously oscillating actuator, a rocker member, connections between the rocker member and the feed dog for imparting up-and-down movement 65 to the latter, a coupling device connecting the actuator with the rocker member, a latch for holding the coupling device inoperative, a vertically yieldable slide for carrying the channeling knife arranged to be raised by a sole on the work sup- 70 port when the latter is raised into operative position, and connections between the slide and the latch for throwing out the latch.

77. In a sole fitting machine, in combination, a support for a sole, a knife for slitting the sole 75

- edge to form a lip and a feather, and a dividing knife constructed and arranged to slit the face of the sole at a point substantially in advance of the edge slitting knife and to cooperate with the latter to form a lip which is narrower than the feather, said dividing knife having an inclined cutting edge sloping upwardly and rearwardly from said edge slitting knife adapting the knife to cut with a drawing action, and said dividing knife being mounted for adjustment in the direction of its inclined cutting edge after grinding of the knife to compensate for shortening of the knife and to maintain the lead of the dividing knife over the edge knife.
- 15 78. In a sole fitting machine, a knife reciprocating in the line of feed of a sole and arranged to cut upon its backward stroke, and sole slashing means arranged to feed the sole against said knife while the knife is moving backwardly and for feeding the sole with said knife during the forward stroke of the knife.
79. In a sole fitting machine, mechanism intermittently operative to slash the surface of a sole and to feed the sole, and means movable opposite to the direction of feed to channel the sole while the sole is being fed by said mechanism and in the direction of feed to impart an auxiliary feed movement to the sole while said mechanism is inoperative.
- 20 80. In a sole fitting machine, two channeling knives, means for moving said knives simultaneously in opposite directions, and two slashing knives, one associated and movable in unison with each channeling knife for feeding a sole while the other channeling knife is cutting the sole in a direction opposite to the direction of feed.
- 25 81. In a sole fitting machine, in combination, a sole support, a knife having a cutting edge parallel to the surface of the sole support for cutting downwardly into the surface of a sole on the support to form a slash extending inwardly from the sole edge and of uniform depth throughout its length, means for operating said knife to feed the sole across said support and to form in the margin of the sole a series of closely adjacent slashes to prepare the sole for the reception of adhesive for securing the sole to a shoe, and means for limiting the depth of the slashes.
- 30 82. In a sole fitting machine, in combination, a sole support, two four-way motion knives arranged to be moved alternately into engagement with the margin of a sole on said support to feed the sole and to form in its margin a series of slashes for preparing the sole margin for the reception of adhesive for securing the sole to a shoe.
- 35 83. In a sole fitting machine, in combination, a sole support, two four-way motion feed dogs arranged to be moved alternately into engagement with a sole on the support to feed the sole, and knives carried by said feed dogs for slitting the surface of the sole to prepare it for the reception of adhesive for securing the sole to a shoe.
- 40 84. In a sole fitting machine, in combination, a sole support, a plurality of cutters arranged to make substantially aligned incisions extending in directions transverse to the sole edge in the marginal surface of a sole, means for feeding the sole over said support to advance the margin of the sole progressively past said cutters, means for operating said cutters to form a plurality of rows of incisions in the sole margin as the sole is fed over the sole support, and means for guiding the sole to cause said rows to extend in directions parallel to the sole edge.
- 45 85. In a sole fitting machine, in combination, a sole support, a plurality of knives arranged to make incisions extending in directions transverse to the sole edge in the marginal surface of a sole, the incisions being located at different distances from the sole edge, and means for operating said knives to feed the sole over the sole support and to form in the sole margin a plurality of rows of incisions, the incisions being arranged close together in the rows and the rows extending parallel to the sole edge. 5
- 50 86. In a sole fitting machine, in combination, a sole support, and means for preparing the marginal surface at the flesh side of the sole for the reception of an adhesive for securing the sole to a shoe by forming along the margin of the sole a series of closely adjacent incisions of uniform depth, the incisions extending in directions substantially normal to the sole edge and terminating short of the sole edge. 20
- 55 87. In a sole fitting machine, in combination, a sole support, a knife arranged to operate upon the margin at the flesh side of a sole on the support to make an incision, the incision extending inwardly from a point spaced from the sole edge, and means for operating said knife to feed the sole over the sole support and to form along the sole margin a series of incisions arranged in closely adjacent relation.
- 60 88. In a sole fitting machine, in combination, a vertically movable channeling knife slide, a channeling knife carried by said slide, a spring tending to move said slide downwardly, means for limiting the downward movement of said slide to locate said knife in a normal position, and mechanism operable upon depression of a treadle to raise said slide to withdraw the channeling knife from the work, said mechanism including a clutch the members of which are adapted to slip after the channeling knife has been raised and while the treadle remains depressed to permit said spring to move said slide downwardly to lower said knife into normal position. 40
- 65 89. In a sole fitting machine, in combination, a vertically movable channeling knife slide, a channeling knife carried by said slide, a spring tending to move said slide downwardly, means for limiting the downward movement of said slide, a rock-shaft, a lifter arm on said rock-shaft arranged to raise said slide against the action of said spring, a clutch member splined on said rock-shaft, a complementary clutch member rotatable on said rock-shaft, treadle-operated mechanism connected with said rotatable clutch member for turning the latter, and a spring tending to hold said clutch members engaged so that the rockshaft will be turned to raise the channeling knife, said spring being weaker than the first spring so as to yield to permit disengagement of the clutch members so that the first spring will thereafter operate to lower said channeling knife. 50
- 70 90. In a sole fitting machine, in combination, a work table for supporting a sole while it is being fed, two carriers mounted to oscillate about axes normal to the surface of the work table and located at opposite sides of the line of work feed, means connecting said carriers to move simultaneously in opposite directions, a main shaft, means including an eccentric on said shaft for oscillating said carriers, an inner channeling knife and an inner feed dog carried by one of said carriers, an outer channeling knife and an outer feed dog carried by the other of said carriers, and means including a second eccentric on said shaft for imparting up-and-down movements to said feed 70
- 75 75

dogs to move them into and out of engagement with the work while they are being moved back and forth by the oscillatory movements of said carriers.

5 91. In a sole fitting machine, in combination, a work table capable of being raised and lowered to move it respectively to and from a normal work supporting position, inner and outer channeling knives capable of being raised and lowered to move them respectively from and to normal operative positions, mechanism constructed and arranged to cooperate with the work table when the latter is in raised position to feed a sole to said knives, and mechanism operable upon depression 10 of a treadle to lower the work table to stop the feed of the work and facilitate its removal from the machine, to raise both channeling knives to enable them to cut out through the face of the sole, and later to lower said knives into position 15 to start operations upon another sole.

92. In a sole fitting machine, in combination, a work table capable of being raised and lowered to move it respectively to and from a normal work supporting position, inner and outer channeling 20 knives capable of being raised and lowered to move them respectively from and to normal operative positions, mechanism constructed and arranged to cooperate with the work table when the latter is in raised position to feed a sole to said knives, and mechanism operable upon depression 25 of a treadle to lower the work table to stop the feed of the work and facilitate its removal from the machine, to raise both channeling knives to enable them to cut out through the face of the sole, and later to lower said knives into position 30 to start operations upon another sole, said mechanism being operable upon release of the treadle to raise the table to return it into normal work supporting position.

40 93. In a sole fitting machine, in combination, a work table capable of being raised and lowered to move it respectively to and from a normal work supporting position, inner and outer channeling knives capable of being raised and lowered to move them respectively from and to normal operative 45 positions, mechanism constructed and arranged to cooperate with the work table when the latter is in raised position to feed a sole to said knives, treadle-operated mechanism for lowering

the work table and for raising both of said knives, and separate treadle-operated mechanism for raising said outer knife independently of the inner knife.

45 94. In a sole fitting machine, in combination, a work table capable of being raised and lowered to move it respectively to and from a normal work supporting position, inner and outer channeling knives capable of being raised and lowered to move them respectively from and to normal operative 10 positions, mechanism constructed and arranged to cooperate with the work table when the latter is in raised position to feed a sole to said knives, treadle-operated mechanism for lowering the work table and for raising both of said knives, 15 and other treadle-operated mechanism for modifying the action of the feed mechanism to vary the rate of work feed.

95. In a sole fitting machine, in combination, a yieldable edge knife slide, an edge knife carried by 20 said slide, an auxiliary slide capable of yielding relatively to said edge knife slide, an edge knife presser gage carried by said auxiliary slide, and means for rigidly connecting said auxiliary edge slide with said edge knife slide to enable the edge 25 knife to yield under the control of said presser gage and thus to adapt the machine for operating upon welt work, said means being operable to disconnect said auxiliary slide and said edge knife slide, to enable the edge knife to yield independently 30 of said presser gage and thus to adapt the machine for operating upon turn work.

96. In a sole fitting machine, in combination, a vertically yieldable edge knife slide, an edge knife carried by said slide, an auxiliary slide 35 mounted within said edge knife slide with provision for vertical movement relatively thereto, a spring tending to move said auxiliary slide downwardly relatively to said edge knife slide, a presser gage for the edge knife carried by said auxiliary 40 slide, and a screw carried by said edge knife slide and adapted to be turned in one direction to engage said auxiliary slide and fixedly secure the latter to said edge knife slide and to be turned 45 in the opposite direction to disconnect said slides so that said presser gage may yield independently of said knife.

FREDERIC E. BERTRAND.
